UNITED STATES PATENT OFFICE

2,513,016

BRUSHMAKING MACHINE

Melvin J. First, Louisville, Ky., assignor to Devoc
& Reynolds Company, Inc., Louisville, Ky., a
corporation of New York

Application September 20, 1947, Serial No. 775,362

50 Claims. (Cl. 300—2)

1

This invention relates to brush machines for manufacturing brushes of the paint brush type, and, more particularly, to automatic machines for manufacturing paint brush units each consisting of a ferrule with a group or "knot" of bristles, and accompany wedge or "plug" mounted therein ready for cementing and the application of the handle.

The general object of the present invention is to improve the construction and operation of the brush machine disclosed in United States patent, No. 2,033,258, issued March 10, 1936, to Lewis W. Simms and Andrew O. Partriquen, and assigned to the same assignee as the present application, to the end that a higher quality of brush may be produced. Machines constructed according to that patent have proven successful and operative in commercial practice, but apparatus embodying the improvements of the present invention, in addition to producing a better brush unit, has greater reliability and a higher rate of production. The improved machine also has numerous other advantages which will be apparent as the description proceeds.

Thus for example one of the specific objects of the invention is to maintain effective control of the bristles to prevent loss both prior to and during the formation of the knot ready for insertion in the ferrule.

Another specific object of the invention is to provide a machine which is capable of making brush units in a greater range of sizes than the former machine, particularly brush units having longer and also shorter bristles, and which machine can be quickly and easily readjusted or rearranged to handle any size of brush and any length of bristle within its range.

Another particular object of the invention is to provide bristle segregating and knot forming and handling mechanism which is capable of being adjusted quickly to all knot widths and thicknesses within the range of the machine.

Another object of the invention is to secure greater uniformity in the quantity of bristles segregated into each knot during the knot formation.

Another object of the invention is to provide a machine which will handle bristles of various grades, that is, those of inferior quality as well as bristles of the better grades.

Another object of the invention is the provision of a machine so constructed as to prevent bristles from fouling its mechanism or interfering with the proper operation of the machine.

Another object of the invention is to prevent

loss of bristles from the knot in the various operations subsequent to the formation of the knot so that the brush units will uniformly have their intended quotas of bristles.

Another object of the invention is to provide more effective control of the bristles during and following the operation of inserting the knot in the ferrule until the knot is fixed in the ferrule.

Another object of the invention is to provide a brush machine which will successfully handle bristles that are long in comparison to their length within the ferrule.

Another object of the invention is to provide more effective control of the wedge or plug member, which frictionally retains the bristle knot in the ferrule, to prevent brush units from issuing from the machine without such members.

In order to carry these objects into effect it has been necessary to reorganize substantially the entire machine commencing with the knot picker mechanism and bristle feed box, although only minor changes have been required in the portion of the machine preceding this mechanism.

The invention will be understood from a consideration of the accompanying drawings which, by way of example, disclose one embodiment thereof. In these drawings:

Figs. 1, 1A and 1B jointly illustrate the complete apparatus in front elevation;

Figs. 2, 2A and 2B jointly illustrate the complete machine in plan view;

Fig. 3 is a vertical section of a detail taken on line 3—3 of Fig. 1;

Fig. 4 is a view in elevation of the automatic bristle feeding and conveyor operating mechanism;

Fig. 4a is an elevation of some of the parts shown in Fig. 4 looking from the left;

Fig. 4b indicates the approximate path of travel of the bristle feed finger;

Fig. 5 is a plan view of the automatic bristle feeding mechanism;

Fig. 6 is a sectional detail taken on line 6—6 of Fig. 4;

Fig. 7 is a sectional elevation, certain parts being broken away, of the feed box and knot picker mechanism taken on line 7—7 of Fig. 9 with the pocket and flag end shaper mechanism ready to receive a knot of bristles;

Fig. 8 is a view somewhat similar to Fig. 7 showing the needle member enclosing a knot of bristles in the bristle pocket device or knot holder, certain parts being omitted, and the section being taken on line 8—8 of Fig. 9;

Fig. 8a (Sheet 14) is an enlarged elevation of

2

the bristle knot holder adapter and insert shown in Fig. 8;

Fig. 8b (Sheet 14) is a sectional view taken on line 8b—8b of Fig. 8a;

Fig. 8c (Sheet 14) is a front view of the knot holder shown in Figs. 8a and 8b;

Fig. 8d (Sheet 14) is an end view of a modified form of such insert;

Fig. 9 is a sectional plan view of the bristle feed box and knot picker or knot forming mechanism taken on line 9—9 of Figs. 7 and 14;

Fig. 10 is a sectional plan of the same mechanism taken on line 10—10 of Figs. 7 and 14 centrally through the bristle feed box and bristle knot holder or pocket device of the knot picker mechanism;

Fig. 11 (Sheet 8) is a fragmentary transverse vertical section taken on line 11—11 of Fig. 8 looking toward the left as indicated;

Fig. 12 is a development section taken on line 12—12 of Fig. 8 showing partial compression of the bristles of the knot;

Fig. 13 is a detail view showing in locked position a finger which is part of a needle carrier and locking mechanism for locking together the needle carrier and the knot picker disc to enable these to move as a unit from loading position to transfer position;

Fig. 14 is a transverse section of the bristle feed box, being taken on line 14—14 of Figs. 7, 9 and 10;

Fig. 15 is a vertical sectional elevation of the knot picker disc and locking mechanism taken on line 15—15 of Fig. 9 and also showing the bristle separator and the movable knot shaper;

Fig. 16 is a vertical section taken on line 16—16 of Figs. 15 and 9 to show the knot picker disc locking mechanism;

Fig. 17 shows a detail of this mechanism, being a vertical section taken on line 17—17 of Fig. 9;

Fig. 18 is an enlarged detail section taken on line 18—18 of Fig. 17;

Fig. 19 is a schematic diagram showing certain parts somewhat distorted in order to indicate the operation of the needle carrier-to-knot picker disc locking mechanism and the knot picker disc locking mechanism. The parts are shown with the bristle pocket at the loading position;

Fig. 20 is a similar view with the disc rotated 90° to move the knot holder to the knot transfer position;

Fig. 21 is a vertical section taken on line 21—21 of Fig. 9 showing parts of the disc locking mechanism;

Fig. 22 (Sheet 1) is an enlarged detail showing the upper and lower pawl bridges of the bristle feed box coacting with the bristle holding pocket;

Fig. 23 (Sheet 1) is a plan view of the lower pawl bridge;

Fig. 24 (Sheet 1) is a detail section of the needle taken on line 24—24 of Fig. 22;

Fig. 25 (Sheet 2) is a detail sectional view taken on line 25—25 of Fig. 2A of the bristle conveyor;

Fig. 26 (Sheet 2) is a detail section taken on line 26—26 of Fig. 25 showing the adjustable support for the outer end of the rear wall of the bristle feed box;

Figs. 27 and 28 (Sheet 4) are respectively an elevation and a plan view of an adjustable edge portion of the roof member of the feed box;

Figs. 29, 30 and 31 (Sheet 4) are respectively

a detail front elevation, plan, and side elevation of the upper and movable part of the knot shaper for the flag end portion of the knot, which cooperates with the adjustable edge portion of Figs. 27 and 28;

Figs. 32, 33 and 34 (Sheet 4) are respectively a front elevation, plan, and side elevation of the flag end floor extension with which the flag end knot shaper cooperates;

Figs. 35 and 36 (Sheet 4) are respectively a front elevation and a plan of the control lever of the disc locking mechanism;

Figs. 37, 38 and 39 (Sheet 4) are respectively a front elevation, plan, and side elevation of the locking lever of the same mechanism;

Fig. 40 (Sheet 12) is a vertical section of the needle operating mechanism taken on line 40—40 of Fig. 2A;

Fig. 41 is a detail section taken on line 41—41 of Fig. 40;

Fig. 42 is a vertical section of the bristle separator operating mechanism taken on line 42—42 of Fig. 2A;

Fig. 43 (Sheet 5) is an enlarged central section of certain parts shown in Figs. 40 and 42;

Fig. 44 is a vertical section taken on line 44—44 of Fig. 2A showing various cams;

Fig. 45 is an enlarged detail section of two co-acting levers shown in Fig. 44;

Fig. 46 is a vertical section taken on line 46—46 of Fig. 2A with parts omitted;

Fig. 47 is a sectional elevation of the knot picker mechanism similar to Figs. 7 and 8 but showing the disc indexed or rotated to the knot transfer position;

Fig. 48 is an elevation of the transfer jaws of Fig. 47 shown in closed position;

Fig. 49 is an elevation of the transfer mechanism parts of Fig. 47 viewed from the left and with jaws closed as shown in Fig. 48;

Fig. 50 is a plan view of the parts shown in Fig. 48 showing the transfer jaws about to remove the bristle knot from the bristle holder of the knot picker disc;

Fig. 51 is a detail section taken on line 51—51 of Fig. 48;

Fig. 52 is a sectional view taken on line 52—52 of Fig. 48;

Figs. 53—56 inclusive show two modified forms of knot transfer jaws;

Fig. 57 is a sectional elevation showing the operating mechanism for the bristle transfer carriage and the entering or transfer patty;

Fig. 58 is a vertical section taken on line 58—58 of Fig. 57;

Fig. 59 is a somewhat enlarged sectional elevation of the entering patty operating mechanism;

Fig. 60 is a rear elevation (looking from the right) of the mechanism shown in Fig. 59;

Fig. 61 is a plan view of the mechanism of Fig. 59;

Figs. 62—67 inclusive are views showing details of the entering patty mechanism;

Fig. 68 is a greatly enlarged view of the mechanism of Fig. 59 showing the entering patty in three of its operating positions;

Fig. 69 is an enlarged elevational view of part of the apparatus of Fig. 1A showing the ferrule feed mechanism with the ferrule feed bar in extreme right-hand position;

Fig. 70 is a sectional plan view of this ferrule feed mechanism taken on line 70—70 of Fig. 69;

Fig. 71 is a sectional vertical elevation of this mechanism taken on line 71—71 of Fig. 70;

Fig. 72 is a sectional elevation taken on line

12-12 of Fig. 70 showing the pivoted right-hand end section of the upper bristle guiding rail in its closed position;

Fig. 73 is a fragmentary elevation showing the positions of various parts with the ferrule feed bar in its extreme left-hand position;

Fig. 74 is a detail section taken on line 74-74 of Fig. 73 and shows the adjustable mounting of the pick-up device of the ferrule feed bar which feeds ferrules from the magazine;

Fig. 75 is a vertical section taken on line 75-75 of Fig. 69, and shows levers which operate the pivoted end-section of the bristle upper guide rail;

Fig. 76 is a vertical section taken on line 76-76 of Fig. 71 and shows the adjustable mounting of the lower bristle guide rail;

Fig. 77 is a vertical section taken on line 77-77 of Fig. 71 showing the carding teeth engaging the bristles of a brush unit to advance the bristles between the guide rails simultaneously with the advance of the ferrule of the unit;

Fig. 78 is a vertical section taken on line 78-78 of Fig. 71 to show the adjustable mounting of the upper bristle rail;

Figs. 79 and 80 (Sheet 11) are detail views of the opening lever for the pivoted upper bristle guide rail section;

Figs. 81 and 82 (Sheet 11) are similar views of the closing lever for such rail section;

Fig. 83 (Sheet 14) is a vertical section taken on line 83-83 of Fig. 2A showing the operating mechanism for raising and lowering the carding teeth supporting bar;

Fig. 84 (Sheet 19) is an enlarged elevation of the carding teeth supporting bar with parts broken away;

Fig. 85 is a plan view of the mechanism shown in Fig. 84 with parts omitted;

Fig. 86 is a horizontal longitudinal section taken on line 86-86 of Fig. 84;

Fig. 87 is a similar section showing a detail taken on line 87-87 of Fig. 84;

Fig. 88 is a vertical transverse section taken on line 88-88 of Fig. 84;

Fig. 89 is a similar section taken on line 89-89 of Fig. 84;

Fig. 90 (Sheet 3) is an enlarged elevation of the plug-inserting mechanism shown in Fig. 1B looking in the direction of the arrows 90-90 of Fig. 91 (Sheet 6);

Fig. 90a shows a modification of some of the parts shown in Fig. 90;

Fig. 91 (Sheet 6) is an enlarged plan view of this mechanism;

Fig. 92 is a detail section taken on line 92-92 of Fig. 90;

Fig. 93 (Sheet 5) is a section taken on line 93-93 of Fig. 2B showing the ferrule stop which is located at the final padding station;

Fig. 94 is an elevation of this ferrule stop;

Fig. 95 is a bottom view of the same;

Figs. 96, 97, and 98 (Sheet 20) are views in transverse longitudinal section of the brush unit (the product of the present machine), showing the unit in different stages of manufacture;

Fig. 99 is a schematic view showing brush units at the various positions or stations to which they are moved by the ferrule feed mechanism;

Fig. 100 is a schematic view to show the location of the bristle trimmer; and

Fig. 101 is a somewhat enlarged view similar to a portion of Fig. 99 to illustrate a modified operation of the apparatus to spread a two inch bristle knot to fill a two and one-half inch ferrule.

Referring now to the accompanying drawings and particularly to Figs. 1, 1A, 1B, 2, 2A and 2B the general arrangement of the machine of the present invention is not unlike that of the apparatus of the patent mentioned above. That is to say, the present machine includes a conveyor for feeding the bristles sidewise in a more or less continuous layer of substantial thickness, the bristles being arranged in generally parallel relation, with their butt ends facing in one direction and their flag ends in the opposite direction. The bristles are placed on this conveyor by hand close to the right-hand end of the machine. The conveyor carries them toward the left through a combing unit indicated generally by reference character A in Figs. 1 and 2, then to a knot picker or knot forming mechanism C (Fig. 1A). The conveyor has an intermittent movement to feed the bristles only as required by knot picker C, and is operated by an automatic bristle feeding and conveyor operating mechanism B (Figs. 1A and 4).

In knot picker mechanism C the bristles are segregated into successive uniform groups, or knots, each containing the desired quantity of bristles to be inserted in a ferrule. The knots are formed with the brush width dimension of the knot vertical, and, by a 90° movement or "indexing" of the knot carrier, are turned to horizontal position for presentation to the ferrule.

The ferrules are fed from the bottom of a ferrule magazine D (Sheets 2, 17 and 18) by means of a ferrule feed mechanism E (Sheets 2, 3 and 17) of the reciprocating conveyor type which feeds the ferrules also towards the left, step by step, through a number of successive, equally spaced positions, or stations, indicated by numerals 1-10 inclusive (Fig. 99, Sheet 20; also Figs. 1A and 1B). At station 1, which is opposite the knot picker mechanism C, the knot is transferred therefrom and inserted in the ferrule by means of a knot transfer mechanism F (Sheets 5 and 13). At this position the bristles are also pushed or patted into the ferrule until they are approximately centered therein as indicated in positions 1 and 2 of Fig. 99 (Sheet 20).

At ferrule position 3 (see also Fig. 99), the bristles are patted farther into the ferrule so that they project from the rear end of the ferrule only a sufficient distance to properly support a fiber or paper plug which the brush unit receives at position 5 from a cardboard inserting mechanism G (Sheets 3, 5, 6 and 20). On advancing to position 6, the bristles are again patted until their butt ends are even with the rear end of the ferrule as shown in Fig. 97 (Sheet 20). Any bristles which still project from the back of the ferrule are then trimmed off by means of an appropriate trimming mechanism H (Sheets 6 and 20) as the brush units are advanced from position 6 to position 7. At position 9 the flag ends of the bristles are engaged by a bristle pulling mechanism I (Sheets 3 and 6) and the knot is pulled to its final position in the ferrule (Fig. 98) (Sheet 20). At position 10 the proper amount of space being left in the ferrule to receive the bristle cement and the brush handle. The brush units at position 10 receive a final combing by a combing mechanism J (Sheets 3 and 6) before being discharged from the machine.

Drive

The machine is driven by means of an electric motor 11 (Fig. 1B) connected by a belt to driven pulley 12 which operates a main shaft 13 through

a clutch mechanism 14. Clutch 14 is arranged to be operated through a yoke 15 by a handle 16. All parts of the machine are operated from this shaft either by direct connection or through speed-reducing units.

Thus a speed-reducing unit 17 (Fig. 2B) is driven from shaft 13 through a chain 18, and its slow-speed shaft 19 is connected through bevel gearing 20 to operate a longitudinal slow-speed shaft 21 which extends from the left-hand end to about the center of the machine. The opposite end of shaft 19 is provided with a small crank 22 which serves to drive ferrule feed mechanism E (Sheets 2, 3, and 17). This is accomplished by means of an adjustable link 23 connected to crank 22 which operates a double armed lever 24 pivoted at 25 to the frame of the machine and connected at its upper end through a link 26 to the ferrule feed mechanism E.

Near the right end of Fig. 2A there is a second speed reducer 27, the input shaft of which is chain and sprocket driven from main shaft 13. Its output or slow-speed shaft 28, at the rear contains a series of cams which actuate certain parts of the knot picker and transfer mechanisms C and F, as will be described further on. The rear end of shaft 28 is supported in a bearing 29 secured to an extension of the machine frame. The portion of shaft 28 in front of speed reducer 27 operates the automatic bristle feeding and conveyor operating mechanism B through two cams 30 and 31 (Fig. 2A).

Bristle conveyor

At the right end of the machine there is a vibrator 32 (Fig. 2) consisting of a vertical flexible plate anchored at the right and to the frame and resiliently held at its opposite end by means of the coil spring shown against a rotary agitator 33 which is driven by means of a belt 34 from main shaft 13. The operator grasps a bunch of the bristles, for example a double handful, and holds their butt ends against vibrator 32 which produces a preliminary straightening or evening of the bristles, after which they are placed upon the bristle conveyor, which consists of two endless chains 35, and spread out in a comparatively thick layer.

These conveyor chains 35 are supported at the right end by a pair of idler sprockets 37 and at their left ends by a pair of driving sprockets 38 (Fig. 2A) secured to an intermittently operated shaft 36 (Figs. 2A and 5) to which motion is imparted at intervals by the automatic mechanism B, the operation of which will be referred to presently. When the bristles are laid by the operator on conveyor chains 35 their butt ends are placed against a vertical stationary guide plate 39 (Fig. 2) and as they are carried toward the left whenever the conveyor chains move they enter between a reciprocating patter 43 and a second vibrator 40 similar to vibrator 32 but formed as a continuation of guide 39. Vibrator 40 is actuated by an agitator 41, driven from shaft 13 by a belt 42 and serves to even the butt ends of the bristles, while patter 43 engages the flag ends of the bristles and is operated more slowly by means of an eccentric 44 on shaft 13. This eccentric, through a connecting rod 45, actuates an adjustable operating mechanism 46 for patter 43. By means of an adjusting handle 47, patter 43 may be made to operate closer to or farther away from vibrator 40 in order to accommodate bristles of different length.

As the conveyor chains continue to move the

bristles toward the left, they are carried through the preliminary combing mechanism A. This mechanism is described in the patent above mentioned and reference to that patent may be had for its full details. It is sufficient to indicate here that the bristles are clamped near their butt ends between one of the conveyor chains 35, the rear chain, and a short endless chain 48 (Fig. 1), which is arranged on a frame 49, that is bodily movable in the vertical direction. The rear chain 35 passes over the upper portion of a large independently driven sprocket whereby the layer of bristles is carried in an upwardly curved path.

Near the top of this path the flag ends of the bristles are acted upon by a comb 51 whose operating mechanism is driven by a belt 52 from main shaft 13, and which moves in an elliptical path. The clamping pressure of the short upper chain 48 against the layer of bristles is provided by means of a tension spring 53. In order to regulate this pressure, the lower end of spring 53 is attached to a lever 54 (Fig. 3) which is pivoted to the frame of the machine at one end, and whose opposite end is held by a clamping screw 55 arranged to be adjustably positioned in a slotted bracket 56 also mounted on the machine frame.

After the bristles pass combing mechanism A they continue in their path toward the left on conveyor chains 35 as these chains are moved forward by mechanism B, and are delivered at the left end of these chains to a bristle feed box 57 (Figs. 2, 4, 8, 10 and 14) which cooperate with and may be considered as a part of the knot picker mechanism C. When the bristles first leave the combing mechanism, they are acted upon by a second vibrator 58 (Fig. 2) which further evens the butt ends of the bristles. This vibrator comprises a strip of leather or other flexible material which is mounted on the end of a stationary but adjustable guide plate 59 that extends to bristle feed box 57, its left end portion constituting the rear wall of this box. Vibrator 58 is operated from shaft 13 by a mechanism similar to that previously described. Guide 60, opposite guide 59, for the flag ends of the bristles operates as a reciprocating patter all the way to feed box 57 and its left end portion constitutes the front wall of this box.

In order to keep the bristles from being displaced as they travel the distance between combing mechanism A and a point near feed box 57, an endless cable 61 (Figs. 1 and 1A) is trained between pulleys 62 and 63, which support the lower side or reach of the cable in proper position above conveyor chains 35 to travel in contact with the upper surface of the layer of bristles. Cable 61 is operated at the same linear speed as chains 35. From the left end of cable 61 to bristle feed box 57 the upper surface of the layer of bristles on conveyor chains 35 is engaged by the lower reach of a pair of short chains 76 (Figs. 1A and 2A) which cooperate with chains 35 in delivering the bristles to the feed box.

The reciprocating patter-guide 60 is mounted on two horizontally adjustable parallel motion mechanisms which are indicated generally by numerals 64 and 64a shown in detail in Fig. 25 (Sheet 2). As shown in this figure, patter-guide 60 is fixed to a short horizontal support 65 which is pivoted to the upper ends of a pair of parallel upright levers 66. These are pivoted below on a horizontally slideable member 67 to form a parallelogram linkage. Member 67 is arranged

to slide in guideways in a support 68 which is fixed to the machine frame. One of the two levers 67 has a lower extension 69 to which the reciprocating motion is imparted by an eccentric 10 on main shaft 13.

By means of these two mechanisms 64 and 64a, operated in unison, guide 60 is made to reciprocate in parallel relation to guide 59 so as to impart to the flag ends of the bristles a patting or pushing motion which is square with the bristles and consequently produces a minimum of bending and a maximum of shifting of the bristles, one with respect to the other, which results in even alignment of the bristles. Slidable member 67 is adjustable by means of a hand-wheel and screw 71 and may be fixed in adjusted position by means of a clamping screw 72. The purpose of this adjustment is to bring patter-guide 60 closer to or farther away from stationary guide 59 when it is desired to set up the machine to operate on longer or shorter bristles.

In order to guide the bristles smoothly past the right end of reciprocating patter 60 an extension 73 (Fig. 2) is hinged to the end. The right-hand portion of extension 73 is supported by means of a short link 74 which swings about the upper end of a vertical rod 75 as the patter reciprocates. The lower end of this rod is supported in a base member which is adjustably mounted on the frame as indicated in Figs. 1 and 2. From feed box 57 the bristles are fed to the cavity or pocket 77 of knot picker mechanism C which segregates a uniform group or knot of bristles from the supply in feed box 57 and takes it to the knot transfer mechanism F as previously referred to.

Automatic bristle feeding and conveyor operating mechanism

The bristles are moved through feed box 57 and into knot picker pocket 77 by means of a vertical feed bar or finger 78 (Figs. 4 and 14). Feed finger 78 is a part of automatic bristle feeding and conveyor operating mechanism B which is shown in some detail in Figs. 4, 5 and 6. This mechanism is fully described in the patent above mentioned to which reference may be had for a complete understanding of its construction and operation. For the purpose of the present invention it is sufficient to note the operating effect of this mechanism.

First of all, bristle feed finger 78 is operated in a square or rectangular vertical path, the corner positions of which are indicated in Fig. 4b, the finger being maintained in an approximately vertical position. Starting with finger 78 in the full-line position shown in Fig. 4b, it first moves downwardly into the mass of bristles within feed box 57 to the position shown in dotted lines at the lower right. Then the finger moves horizontally towards the left on its feeding stroke, after which it is raised to the upper left-hand position, and then carried horizontally to the right to complete the cycle. The length of the feeding stroke depends upon the size of the bristle pocket 77 which may be varied substantially both in width and depth as will be referred to later on. The length of this stroke is automatically controlled by mechanism B, through the resistance of the bristles encountered by finger 78, so that the forward feeding movement of finger 78 ceases when the pocket 77 has been filled with bristles.

Automatic mechanism B also controls, through a ratchet and driving pawl 80 (Fig. 4) the intermittent feeding movement of conveyor chains 35,

ratchet wheel 79 being drivingly connected through a yielding driving mechanism indicated generally by numeral 81 with shaft 39 for driving sprockets 38 of the conveyor chains. Thus the automatic bristle feeding and conveyor operating mechanism B not only automatically feeds the appropriate quantity of bristles into pocket 77 of knot picker C, but also automatically operates conveyor chains 35 to advance the correct quantity of bristles to feed box 57 to take the place of those which have been fed into the knot picker pocket. The operation is carried on in such a manner as to avoid either congestion or a scarcity of bristles in the bristle feed box.

The force to move bristle feed finger 78 and also the feed pawl 80 is supplied by means of a large tension spring 82 (Figs. 4 and 1A) which operates through the system of levers and linkages shown in Figs. 4 and 5 and under the control of cams 30 and 31.

When it is desired to set up the apparatus to operate on a smaller or larger brush, thus necessitating a substantial change in the size of knot picker pocket 77, it is necessary to adjust the extent of movement of conveyor chains 35 for each feed stroke of feed finger 78. This may be accomplished by the mechanism shown in Fig. 4 for changing the stroke of pawl 80. Pawl 80 is mounted on the upper end of a rock arm 83 pivoted on shaft 39. Rock arm 83 is reciprocated by a link 84 simultaneously with each stroke of feed finger 78. In order to vary the stroke of pawl 80 the left end of link 84 is connected to rock arm 83 by means of a block which is split into two sections 85, 85 as shown in Fig. 6 and which is longitudinally shiftable in a slot 86 in rock arm 83.

A stepped pivot pin 87 serves to connect the left-hand end of link 84 with rock arm 83 through split block 85, 85. A threaded rod 88 (Fig. 4) connected at its lower end to block 85, 85 may be shifted by turning the knurled nut 89 to vary the distance of the block and pivot pin 87 from the center of shaft 39 thereby changing the length of the stroke of pawl 80. The two halves of block 85, 85 may be clamped in the adjusted position by turning up on a clamping nut 90 threaded onto the outer end of pivot pin 87 which operates through the bushing shown in Fig. 6 to clamp together the two halves of block 85, 85. The operating spring 82 of this automatic mechanism B is provided with an adjustable mounting at its lower end similar to that shown and described in connection with Fig. 3.

Bristle feed box

Referring now more particularly to Figs. 7-10 and 14 the parts of feed box 57 aside from its front and rear walls, which are formed by guides 59 and 60, are supported on an upright bracket member 91 bolted to the machine frame. The feed box has a lower part or floor member 92 which is fixed in position by being secured to bracket 91.

On the upper face of floor member 92 are secured by screws shown in Fig. 10 two thin metal members 93, 94 whose right end portions extend, one between the chains 35 and the other along the rear side of the rear chain. These two extensions of members 93, 94 respectively serve to receive the bristles from the conveyor chains, the former supporting the central portions of the bristles and the latter the butt end portions. Members 93, 94 are mounted in shallow recesses in the upper surface of floor member 92 so that

11

the feed box floor surface is smooth and level from side to side, that is from the rear edge of member 94 to the front edge of member 93, with the exception of an elongated slot 95 (Fig. 14) which is provided in the upper surface of member 92 in which the lower end of bristle feed finger 78 operates during its feeding stroke. The provision of this slot insures that even the lowermost bristles shall be fed forward by the finger.

This feed box floor construction is intended to support the bristles substantially from end to end as they are moved from the conveyor chains 35 through the feed box, thus preventing the bristles from sagging either at their ends or at the center. In order to prevent such sagging after the bristles are received in pocket 11, member 94 has an extension at the left as shown in Fig. 10 beyond the maximum depth of pocket 11. Also on the flag end side of pocket 11 a laterally adjustable floor extension member 96 (Figs. 7, 10 and 32) is provided. This is a narrow member, being only about one-quarter (1/4) of an inch wide for a reason which will appear later. It is slotted in its upper surface as shown in Figs. 10 and 32-34 for a reason which also will appear presently. Floor extension member 96 is provided with a supporting shank 97 (Fig. 14) which is dovetailed on its inner surface as shown in Fig. 32 and mounted in a dovetailed guide 98 (Fig. 7) on floor member 92. A screw 99 operating through a slot in shank 97 holds the device in adjusted position. Member 96 is adjusted to a point as close to the flag ends of the bristles as possible so as not to interfere with the movement of reciprocating guide 60.

The rear bristle guide 59, the left end portion of which forms the rear wall or "backboard" of bristle feed box 57, is mounted so as to be adjustable laterally of the feed box in order to place the butt ends of the bristles in proper relation to the rear edge of knot picker pocket 11. For this purpose there is attached to the rear of guide 59 a supporting member 100 having a slotted lug 101 to receive a clamping screw 102 which is threaded at its lower end into a tapped hole in floor member 92 (Figs. 10 and 14). To facilitate positioning the edge of guide 59 level with floor 92 at all points the left end of guide 59 is arranged with a two-directional adjustable support 104 shown in Figs. 25 and 26, and also in Fig. 2A.

A rod 105 (Fig. 25, Sheet 2) fixed to the rear of guide 59 is adjustable in a socket 106 having clamping screws 107, thus providing for shifting guide 59 according to the length of bristles being handled by the machine. In turn, socket 106 is vertically adjustable since it is provided with a slotted supporting shank 108 which is clamped to an adjacent part of the machine frame by means of a nut on a bolt 109 (Fig. 2A) which passes through the slot in shank 108. Hence the right end of guide 59 can be adjusted vertically to place its lower edge in accurate level contact with the entire length of the floor of feed box 57.

Feed box 57 has a roof member 110 (Fig. 14) which is supported in vertically slideable arrangement on the upper portion of bracket 91 and can be adjusted by means of a hand screw 111 to vary the height of the bristle space within the feed box. A clamping screw 112 secures the roof member firmly after the adjustment has been made. Such adjustment may be required when changing from one width brush to another width. Roof member 110 is provided with a narrow elongated slot 113 through which feed finger 78

5

operates (Fig. 9). In order to guide the bristles into feed box 57, roof member 110 is preferably provided with an upwardly flared entrance lip which may have an extension 115 (Fig. 7) secured to it. There also may be provided on the rear side of roof member 110 an edgewise acting bristle guide 115a (Figs. 7 and 9) which engages the butt ends of the bristles that project beyond the rear conveyor chain 35.

10

12

Knot picker mechanism

The present brush machine is intended to manufacture brush units for brushes from one-half inch to two and one-half inches (1/2" to 2 1/2") in width and having bristles which may vary from one and seven-eighths inches to three and three-quarters inches (1 7/8" to 3 3/4") in length. The thickness of the brushes varies to correspond to the brush size and type, for example from about one-eighth inch to five-eighths inch (1/8" to 5/8"). Accordingly the knot picker mechanism C is so constructed, along with the other parts of the apparatus, as to accommodate bristle knots of different dimensions comprising various amounts of bristles as well as bristles of different length.

The knot picker pocket 11 is a recess formed in a bristle knot holder or pocket device indicated generally by reference numeral 116, shown in detail in Figs. 8a, 8b and 8c (Sheet 14), and which is mounted on a knot carrier 117 in the form of a circular disc (Figs. 1A, and 7-10). Pocket device 116 consists of two principal parts, a fixed member or "adapter" 118 and a replaceable "insert" member 123.

Adapter 118 is an L-shaped member as viewed in Fig. 8b having an inwardly extending flange portion 119 and a lateral portion 120. Lateral portion 120 is provided with a U-shaped recess 121 (Fig. 8a) formed by upper and lower jaw portions. This lateral portion 120 is received in a notch cut in the edge of disc 117 of sufficient depth to make the outer arcuate edges of these jaw portions flush with the circular rim or edge of the disc. The adapter 118 is secured to disc 117 by means of a pair of screws 122 which hold flange portion 119 against the face of the disc (Fig. 8, Sheet 8). Recess 121 is approximately 1" in depth and 2" in width, and in making large brushes it constitutes the knot picker pocket 11. However, when making all but the larger size brushes this large recess 121 is reduced in area by mounting an insert member 123 within it so as to form a pocket 11 of appropriate size.

Insert member 123 comprises a block portion 124 usually having a flange or lip 125 along its upper edge, but lip 125 may be omitted, as in the modified insert member 123a shown in Fig. 8d, when it is desired to use a knot picker pocket having maximum width but having less than the maximum depth.

The flange or lip portion 125 of the insert member serves to reduce the width of recess 121, while the block portion 124 functions to build up the bottom of this recess so as to make the knot picker pocket shallower. A graduated series of these inserts may be provided, each having a block portion 124 of different thickness and also having lip portions 125 of varying thicknesses, to alter the size of the U-shaped recess 121 to receive bristle knots of the proper dimensions for the various standard sizes of brushes within the range of the machine. When it is desired to set up the machine to produce any particular size

50

60

65

70

75

of brush, the corresponding insert will be placed within U-shaped recess 121.

Adapter 118 and the inserts are so constructed that an insert may be readily removed and replaced by another of different size. Thus each of the inserts has a dovetailed extension 126 on the bottom of its block portion 124 which is arranged to fit within a dovetail groove 127 extending lengthwise of the bottom of U-shaped recess 121. The inserts may therefore be slid laterally out of or into this pocket. They are held therein in operating position by means of two spring-biased friction pins 128 which are arranged in apertures drilled edgewise through flange portion 119 of the adapter. The outer ends of pins 128 enter shallow recesses 129 in the bottom of the insert member.

In insert 123 in Figs. 8a, 8b and 8c, an adjustable false bottom member 130 is added so that the depth of bristle holding recess 77 can be adjusted without removing the insert member. This construction reduces the number of different insert members for a given complement of brush knot thicknesses. It will be understood that this false bottom member may also be used with insert member 123a.

False bottom member 130 is a rigid metal plate having a cylindrical shank portion 131 projecting at right angles to its surface and received in a cylindrical bore of corresponding size in the block portion 124 of insert 123. Shank 131 has a central threaded aperture extending entirely through the shank to the face of block member 124 and within this fits an adjusting screw 132. The end of this screw bears against the bottom of U-shaped pocket 121 of the adapter, and at its outer end has a multi-sided recess 133 to receive an adjusting tool. By means of this screw adjustment the depth of knot picker pocket 77 can be altered minutely as is sometimes required to meet different brush specifications. False bottom 130 may be locked in the position to which it has been adjusted, by means of a set screw 134 whose inner end is arranged to engage the surface of shank 131.

By employing insert members such as just described having only a single lip 125 or 125a along its upper edge, the lower jaw of U-shaped recess 121 serves as one of the side walls of knot picker pocket 77 for all of the various sizes of pockets. This simplifies the construction and operation of the knot picker carrier disc 117 since for all brush unit sizes, the lower surface of U-shaped pocket 121 is always brought to the same elevation as the surface of the floor of bristle feed box 57 when the carrier disc is at the bristle receiving position, as shown in Figs. 7 and 8. Both the lower portion of adapter 118 and the lower portion of the inserts 123, 123a are slotted as indicated at 135 in Fig. 8c for a purpose which will presently appear.

With pocket 77 in the receiving position (Figs. 7 and 8) bristles are fed from feed box 57 into the pocket by feed finger 78. Thereupon pocket 77 is closed by an arcuate blade-like member or needle 136 which tapers to a thin point at its upper end as shown in Fig. 8, the needle having closed the pocket and segregated the knot of bristles from the supply within feed box 57. Needle 136 conforms to the curvature of the edge of knot picker disc 117 and moves along this edge from its open position as shown in Figs. 7 and 19 to its closed position just mentioned. Needle 136 is mounted on a carrier member 137 in the

form of a segment having an arcuate surface of the same radius as the radius of disc 117 and on which needle 136 is secured by means of screws 138 as shown in Fig. 11.

Needle carrier 137 is keyed on the front end of a sleeve shaft 139 within which a solid shaft 140 operates (Figs. 8, 40, 41 and 42). These two shafts extend transversely of the machine as shown more particularly in Fig. 2A. Knot picker disc 117 is supported loosely on sleeve shaft 139 and has secured to its rear surface a double flanged member 141 to the rear of which a locking disc 142 is secured. These parts are held together by screws as shown in section in Fig. 10. Knot picker disc 117 is limited in its angular movement of partial rotation to an angle of approximately 90°, to carry the bristle pocket from the receiving position of Figs. 7 and 9 to the upper or transfer position of Figs. 20 and 47 where the bristle knot is in alignment with the ferrule at ferrule station 1 and is ready to be taken by the transfer mechanism and inserted in this ferrule. Thus the knot picker mechanism serves both to form the bristle knot and to align it with the ferrule.

The limits of this angular movement of disc 117 are determined by the disc automatic locking mechanism, which is to be described in detail later, and by means of two stationary stop members 141a and 141b (Fig. 7) which are adapted to be engaged by a block 141c mounted in fixed position on the rear surface of disc 117 (Figs. 7 and 9). The latter stop means supplements the action of the disc locking mechanism and insures that the knot picker pocket 77 will be aligned first with the floor 92 of bristle pocket 57 and then with ferrule station 1 and the knot transfer mechanism.

In connection with the disc automatic locking mechanism it is sufficient for the present to state that it includes a locking disc 142 (Figs. 16 and 20), which is secured by screws (Fig. 21) to the double flanged member 141 which in turn is secured to the rear surface of disc 117 and may be considered as its hub, and that locking disc 142 has in its peripheral face two notches 143 and 144 (Fig. 20) either of which may be engaged by the nose of a latching lever 145 (Fig. 19) biased against the edge of disc 142. When bristle holding pocket 77 is in the receiving or loading position notch 143 is engaged by locking lever 145, and when the pocket is in the transfer or unloading position notch 144 is similarly engaged by this latch member.

The oscillation of disc 117 is imparted to it by needle carrier 137 which has a tail portion 146 (Fig. 8), from the upper and lower faces of which project two yielding driving pins 147 and 148. These pins are adapted to engage lugs 149 and 150 projecting from the face of disc 117, these lugs being in the form of screws for the purpose of adjustment. Therefore when tubular shaft 139 is oscillated to move needle carrier 137 in a counterclockwise direction as viewed in Fig. 8, driving pin 147 engages lug 149 and moves disc 117 90° to carry pocket 77 to the transfer position shown in Fig. 47.

On the reverse movement, pin 147 leaves lug 149 and driving pin 148, engages lug 150 to return knot picker disc 117 to the receiving position. The relative movement between the needle carrier 137 and knot carrier 117 occasioned by the difference in the spread between lugs 149, 150 and driving pins 147, 148 is utilized to open pocket 77 and release the bristles at the transfer posi-

tion of Fig. 47 and to close the pocket and separate the bristles at the receiving position of Fig. 8.

In order to bridge the gap between the surface of knot holder 116 which contains bristle pocket 11, and the end of bristle feed box 57 during the movement of the bristles from feed box 57 into pocket 11, two pivoted bridge pawls 151, 152 are provided as shown in Figs. 8 and 22 (Sheet 1). These pawls are pivoted at their outer extremities, one to the floor member 92 and the other to roofing member 110 and are biased towards disc 117 by means of the coil spring shown in dotted lines in Fig. 8. These members prevent the escape of bristles either below or above. They move back slightly under the camming action of the tapered end of needle 136 when it moves upward to close pocket 11. As a further means of preventing the escape of bristles and also to prevent damage to them, needle 136 is provided with an outwardly projecting lip 153 (Fig. 24) and the pawl bridge members 151, 152 are grooved as indicated in dotted lines in Fig. 22, the groove in lower pawl member 151 being shown in enlarged view in Fig. 23 (Sheet 1).

The oscillating or angular motion of needle carrier 137 which is keyed to sleeve shaft 139 is imparted through the rack and pinion mechanism shown in Figs. 40 and 41, and by a needle carrier operating cam 154 on shaft 28 of the speed reducer 27 (Fig. 2A). Rack member 155 is supplied with teeth on its lower surface near its left end (Fig. 40) which coact with the teeth of a pinion 156 which is keyed to tubular shaft 139. This rack slides in a supporting casing 157 mounted at the rear of the machine as shown in Fig. 2A. At its right end rack member 155 has an L-shaped bracket 158 (Fig. 43, Sheet 5) which is longitudinally adjustable with respect to rack 155 by means of the sliding connection and a pair of screws shown in detail in Fig. 43.

With the cam follower roller 159 mounted on the lower part of bracket 158 in contact with the cam, this enables the effective length of rack 155 to be adjusted so as to position the point of needle 136 flush with or slightly below the bottom of bristle pocket 11 as shown in Figs. 19 and 7, so that the bristles may be fed from feed box 57 by feed finger 78 into a fully open pocket. The dwell of cam 154 is such that the needle remains in such position until the filling of the pocket is completed. Rack 155 is biased toward the right to maintain roller 159 in contact with cam 154 by means of a compression spring 160 located at the bottom of a longitudinal bore in the rack member which extends from its left end (Fig. 40). Spring 160 reacts against the inner end of a rod 161 which projects into the bore and is adjustably mounted on a plug 162 which is threaded into a bracket on the machine frame. Vertical tension spring 160a (Figs. 46 and 1A) supplements the action of spring 160.

Bristle knot compression

The bristles of the knot are held within pocket 11 solely by friction and although knot holder 116 containing pocket 11 engages the bristles along a considerable portion of their length (Fig. 11), it is desirable to make certain that bristles will not be lost from the pocket during the indexing or 90° movement of knot picker disc 117. Accordingly provision is made for compressing the bristles in pocket 11 to compress the whole knot to less than the width of the pocket before the indexing movement takes place. This is accomplished by means of an arcuate compressing

member 163 which is mounted on needle carrier 137 (Figs. 8 and 12).

Its upper end enters slot 135 in the lower part of knot holder 116 (Figs. 8, 11 and 12), after the point of needle 136 has closed over the bristles within the knot holder pocket 11, and forces the lower side of the knot upwardly away from the bottom of the pocket. This is indicated in all three of these figures and causes the bristles to be squeezed so tightly in the knot that there is no danger of any escaping during the indexing movement. Compressing member 163 has a slotted adjustable mounting on carrier 137 to vary the extent of bristle compression, as shown in Figs. 12 and 19.

This bristle compression takes place while disc 117 remains locked by latch 145 (Fig. 16) as previously referred to. Due to the resiliency of the bristles, as soon as latch 145 is released to permit the indexing movement of disc 117, there is a tendency for the disc to rotate forward slightly with respect to needle carrier 137, thereby reducing the compression of the bristles. To overcome this a compression locking lever 164 is pivoted on the front face of disc 117 as shown in Fig. 8, the lower end of the lever being adapted to engage a triangular lug 165 on the end of tail portion 146 of the needle carrier.

In Fig. 8 the interlocking of these two parts is just commencing, driving pin 147 not having yet contacted lug 149. As soon, however, as this takes place locking lever 164 will have been shifted slightly by means of its actuating spring into the position shown in Fig. 13 where the interlocking of the needle carrier 137 and disc 117 is complete. The indexing motion of disc 117 can therefore take place with these two members thus interlocked so as to maintain the desired compression of the bristle knot. As soon as disc 117 reaches the position shown in Fig. 20, the transfer position where the knot of bristles is at the top, compression lock member 164 is automatically released by the engagement of its tail portion 166 with a stationary roller 167, so that relative movement of needle carrier 137 and disc 117 can again take place.

Bristle knot shaping

When operating with long bristles, even though they receive considerable support from bristle holder 116, nevertheless their flag end portions project some distance from the end of the holder, as can be seen for example in Figs. 11 and 12. Consequently there is a tendency for the flag end of the knot to sag and distort sidewise, the illustrations in these two figures being ideal rather than actual. Floor extension 96 (Fig. 7) supports the lower part of the knot against sagging but does not overcome the tendency of the knot to distort sidewise.

To overcome this tendency and to maintain the flag end of the knot in the form corresponding to the configuration of pocket 11, a movable knot support or shaping device 168 for the flag end portion of the bristles is provided. See Figs. 7; also 29, 30 and 31 (Sheet 4). This is a narrow T-shaped member of the same width as floor extension 96 and its vertical bar portion 169 engages the vertical outer surface of the bristle knot being positioned in alignment with the left wall of recess 11 when knot shaper 168 is in the full line position shown in Fig. 7.

The horizontal bar of T-shaped member 168 serves two purposes; that portion at the right serves to shape the top of the knot and corre-

sponds with the upper edge of pocket 77, while that portion at the left is bolted at 170 to secure the knot shaping device to its support 171. Device 168 is horizontally adjustable by a sliding connection associated with the upper end of support 171. It is vertically adjustable through a slide connection of support 171 with an operating arm 172 which serves to swing shaping device 168 from the full line or operative position shown in Fig. 7 to the dotted line or inoperative position, in order to permit the bristle knot to be moved to the transfer position by the indexing of the knot picker disc 117. Support 171 is secured in position on arm 172 by means of a clamping screw 173.

The lower end of vertical bar portion 169 of the shaping device is provided with a narrow tongue 174 (Figs. 29 and 30) which enters the slot in the upper surface of floor extension member 96 when shaping device 168 is at its operative position. This forms a joint between these two parts which prevents escape and injury to the bristles. The horizontal upper portion of shaping device 168 is sloped at its end as indicated at 175 in Fig. 29 in order to coact with a similarly sloping surface 176 of a part 177 (Figs. 27 and 28 which is mounted upon the lower part of roof member 110 of bristle feed box 57 (see Fig. 7). These cooperating sloping surfaces 175, 176 constitute a joint under which the bristles may slide without being twisted or cut as they move from feed box 57 into pocket 77.

Both the part 177 and movable shaping device 168 are adjustable transversely of the machine so that they can be positioned close to the flag ends of the bristles and adjacent the patter-guide 60, regardless of whether the machine is running short bristles or long bristles. This adjustment is accomplished for member 177 by means of a sliding joint, shown in Figs. 7 and 9, and a small screw which operates through a slot in member 177 to hold the member in position. The lateral adjustment of movable shaper 168 is provided by longitudinal movement of a transverse shaft 178 (Fig. 15) which supports and operates arm 172.

Shaft 178 is supported in a bearing bracket 179 which is secured to the machine frame, and also in a bearing (not shown) at the rear side of the machine. The front end of shaft 178 is threaded to receive a knurled adjusting nut 180 which coacts with the side of bearing 179 to move shaft 178 in one direction, while a coil spring 181 shifts the shaft in the opposite direction. By means of this adjustment, arm 172 may be shifted to position movable shaping device 168 to accommodate bristles of different length.

The actuation of arm 172 from the full line position of Fig. 7 to the dotted line position is effected by a rocking movement of shaft 178. This is produced by means of a cam 182 on knot picker cam shaft 28 on the rear side of speed reducer 27 (Figs. 2A and 44). As shown in the latter figure, cam 182 operates shaft 178 through a double-arm lever 183 which is pivoted to the machine frame and which operates an arm 184 fixed to shaft 178 through a yielding plunger 185 (Fig. 45). Plunger 185 coacts with an elongated pad 186 on arm 184, the length of this pad being sufficient to actuate arm 178 in any longitudinal position to which it may be adjusted by adjusting nut 180 previously referred to. Cam 182 is shaped and mounted on shaft 28 in such position as to time the withdrawing movement

of removable knot shaper 168 just prior to the indexing movement of knot picker disc 117 towards the transfer position.

Bristle separating

The knot picker mechanism of the present machine is provided with a bristle separator or spreading device in the form of a slender tapered finger 187 (Figs. 8, 11 and 15). When operating on the longer bristles, or with bristles of inferior quality, the flag ends of the bristles in the knot may not be completely separated or segregated from the mass of bristles in feed box 57 merely by the operation of needle 136 enclosing pocket 77 since this needle operates toward the butt ends of the bristles rather than toward the flag ends. If complete separation is not effected prior to the indexing movement of knot picker disc 117, some of the bristles of the knot are apt to be dragged from pocket 77 by their entanglement with the bristles in the feed box. Also bristles are apt to be pulled out of the feed box, resulting in both an incomplete bristle knot being transferred to a ferrule, and also in the loss of bristles. Bristle separator 187 prevents this from occurring.

The supporting and operating mechanism for separator 187 causes the separator to move in a combined downward and outward motion (toward the left of Fig. 11) along the front edge 30 of needle 136 until the point of the separator has passed through the mass of bristles. Thereafter it imparts to the separator an outward movement lengthwise of the bristles, the separator being subjected to a rapid lateral vibratory action during this movement. The result is to effect complete separation of the flag end portions of the bristles in the knot from those in the feed box.

This separator operating mechanism comprises a supporting arm 188 which is clamped as shown in Fig. 7 fast to the outer end of shaft 140, this being the shaft which operates within the sleeve shaft 139 operating needle carrier 137. A fluid pressure operated vibrator device 189 is mounted 40 on arm 188 to which air or other fluid under pressure is supplied at appropriate times through a flexible conduit 190. The operation of this vibrator causes a rapid radial vibratory movement of the outer end portion 191 of arm 188, 50 separator 187 being appropriately fixed to such outer end portion 191 as shown in Figs. 7 and 15. The supply hose 190 is connected to a suitable supply of fluid under pressure through a control valve 192 (Figs. 2A and 44) which is automatically operated by means of a face cam 193 projecting rearwardly from a cam disc on shaft 28 (see also Fig. 44).

In order to operate supporting arm 188, shaft 60 140 is given both an angular and a longitudinal movement. The angular movement is produced by the rack and pinion mechanism shown in Fig. 42 which is identical with that described previously in connection with Fig. 40, the only difference being the fact that the operating pinion 194 is keyed to shaft 140 (Fig. 41) and that rack 194 is actuated by a cam 196 having a different configuration from that of cam 154. Cam 196 is mounted adjacent to cam 154 on shaft 28. The adjustment in the effective length 65 of rack 195 is the same as described in connection with rack 155 and enables the position of the point of separator 187 to be adjusted to produce accurate timing of its operation in connection with the movement of needle 136 and

the other parts of the knot picker mechanism.

The longitudinal movement of shaft 140 is produced by means of a face cam 197 (Fig. 2A) on the opposite side of the cam disc from cam 193 and which cooperates with a roller 198 on a pivoted horizontal lever 199, the opposite end of which is connected to the rear end of shaft 140 through a yoke and grooved collar 200. A tension spring 201 biases lever 199 and shaft 140 towards the front of the apparatus. Thus the forward stroke of separator 187 which causes the separation of the bristles takes place under the yielding action of spring 201, the return stroke being under the positive movement of cam 197.

In Fig. 15 separator 187 is shown on its return stroke as indicated by the arrow, and in Fig. 11 the full line position of separator 187 indicates the end of its return stroke where it remains until the next knot of bristles has been segregated by the needle 136. Then the point of the separator moves downwardly and at the same time towards the left following the sloping edge of needle 136 and entering the opening in the bristles formed by the thickness of the needle. The dotted position of separator 187 in Fig. 11 shows the separator at the end of its separating stroke which is adjusted to be close to the movable flag end shaper 168 and floor extension 96 and consequently about one-quarter of an inch ($\frac{1}{4}$ ") from the ends of the bristles.

This adjustment of the outward stroke of separator 187 is made by means of a stop screw 202 (Figs. 9 and 15) which is engaged by the left end of shaft 140 and limits the lengthwise motion of this shaft, and consequently of separator 187, under the tension of spring 201 and control movement of cam 197. When stop screw 202 is adjusted to arrest the movement of shaft 140 at less than the maximum movement produced by cam 197, roller 198 merely leaves the surface of the cam at the instant of contact of shaft 140 with the stop screw.

Separator 187, after being moved forward toward the left (Figs. 11 and 15) while in the bristles by the action of spring 201, remains in the bristles and in its down position while the knot picker disc 117 is indexing, and acts as a barrier to prevent bristles in feed box 57 from being drawn out by entanglement with bristles in knot picker pocket 77, and likewise prevents bristles in feed box 57 from pulling bristles from pocket 77. This barrier action of separator 187 is maintained as long as possible or until needle 136 is about ready to segregate the succeeding knot. That is to say, when pocket 77 is ready to receive bristles from feed box 57 separator 187 must be lifted out of the way of the bristles, but at all other times the separator is left in its down position acting as a barrier to assist in keeping the bristles in feed box 57.

The separation of the butt end portions of the bristles in the knot from those of the mass in feed box 57 is accomplished by needle 136 since the butt ends separate more easily than the flag ends and moreover they do not project so far from the rear edge of knot holder 116 as the flag end portions (Fig. 11). When the machine is operating on extremely long bristles, however, in which case the backboard guide 59 is adjusted rearwardly to a considerable distance from the rear of knot holder 116, a needle having an extended rear margin and a skew chisel-shaped contour is used in place of the standard pointed needle. In fact, such a needle is shown in Figs.

11 and 15, the extended margin being indicated by numeral 203 and the chisel-shaped point at 204.

Automatic knot carrier locking mechanism

It was mentioned previously that knot carrier disc 117 is locked against rotation during the time it is at the receiving or loading position and during the time it is at the transfer or unloading position. It was also stated that this locking is accomplished by means of latching lever 145 engaging either of two notches 143 or 144 in locking disc 142 (Fig. 16) which is mounted on the rear of double flanged hub 141 of knot picker disc 117 (Figs. 10 and 21). Latching lever 145 is pivoted at its upper end at 205 to an extension of a bearing bracket 206 (Fig. 16) which supports shaft 139 for needle carrier 137, the hub of which is keyed to this shaft at its outer end. Mounted on the same pivot pin 205 is a control lever 207 which controls latching lever 145.

Control lever 207 is biased downwardly by a tension spring 208 and is limited in its downward movement by the engagement of the lower end of an adjustable stop screw 209 with a suitable boss on bearing bracket 206. Lever 207 is operatively connected with latching lever 145 by means of a compression spring 210 on the upper side of pivot pin 205, and, on the lower side of the pivot, by means of a positive connection in the form of an abutment which engages the right end of an adjustable screw 211 threaded through an aperture in lever 145. Consequently downward movement of control lever 207 will immediately shift the nose of latching lever 145 out of its notch in locking disc 142, while upward movement of lever 207 merely compresses spring 210 and biases the nose against the face of disc 142.

Referring to Figs. 9 and 15 at the rear bearing bracket 206 there is a latch release disc 212 which is fixed to needle carrier shaft 139 but angularly adjustable with respect thereto by the arrangement here shown. The hub of latch release disc 212 is loose on shaft 139, but immediately to the rear of this hub is a collar 213 (Fig. 21) which is keyed to shaft 139 and which has a pair of upstanding ears 214, each of which extends longitudinally of the shaft a short distance towards latch release disc 212 so that they enclose between them an upward projection 215 on the hub of disc 212. Adjusting screws 216 (Fig. 9) provided, one in each ear 214, are set tightly against the sides of projection 215.

Latch release disc 212 carries two latch release blocks 217 and 218 (Fig. 17) which are of hardened steel and which are mounted in angularly adjustable position on the outer face of disc 212 as indicated in Figs. 17 and 18. Control lever 207 has secured to its lower face vertically above the center of shaft 139 a hardened steel latch release member 219, the inner end of which is shown in Figs. 18 and 21, and under certain conditions may be engaged by either of the release blocks 217, 218.

The purpose of this mechanism is to time the release of locking lever 145 when disc 117 is at the loading position and ready to be indexed toward the unloading position, and also when the disc is at the unloading position and ready to be indexed back to the loading position. Immediately after each release of latching member 145 the latching mechanism is reset by the engagement of a cam 220 with a roller 221 on the front of control lever 207, cam 220 being located

on the peripheral face of locking disc 142 which contains the locking notches 143, 144.

Operation of knot picker mechanism

With knot picker disc 117 in the loading position, that is with pocket 77 at the right (Fig. 19), locking lever 145 is engaged in notch 143 to hold the disc locked. Bristle feed finger 78 now moves bristles from the feed box 57 into pocket 77 whereupon needle 136, the tip of which is at the angular position shown at *o* in Fig. 19, commences to move counterclockwise under the rotation of shaft 139 and needle carrier 137 by needle operating cam 154. The point of the needle pushes through the bristles and closes the pocket. The feed finger is arranged to engage the bristles approximately midway of their length.

When the needle point reaches the angular position *x*, compression of the bristles commences by the operation of compressing member 163 (Figs. 8 and 12), this position being that in which the largest size of pocket 77 is somewhat more than fully closed by the needle.

When needle 136 reaches position *x* compression locking lever 164 partially engages triangular lug 165 (Fig. 8). During this needle movement latch release member 219 has reacted upon latch release block 217 (Fig. 21) which has moved from the position in which the block is shown in Fig. 19 in full outline dotted, towards the left to the position shown by the dotted lines indicating the wedge-shaped head of block 217, in which position the right edge of the block is about one-sixteenth of an inch ($\frac{1}{16}$ ") from the left edge of latch release member 219.

The needle carrier 137 dwells here (needle at position *x*) while the operation of the separator 187 takes place. After the operating movement of separator 187 is completed needle 136 advances and reaches the angular position *y*, and the latch release block 217 passes the left edge of latch release member 219 and thereby allows member 219 to fall. Control lever 207 now moves downwardly under the tension of spring 208 and this throws locking lever 145 to the left out of notch 143 thereby unlocking knot picker disc 117. Further slight motion of needle carrier 137 brings driving pin 147 into contact with lug or screw 149. During this slight motion locking lever 164 has shifted to the position shown in Fig. 13 into full engagement with triangular shaped lug 165 to completely lock the compressed bristles. Thereafter needle carrier 137 and disc 117 move as a unit to the unloading or transfer position (Figs. 20 and 47).

During the first part of this movement the left rise of resetting cam 220 engages roller 221 and lifts control lever 207 to its former position thereby compressing spring 210 (Fig. 16). This biases latching lever 145 against the edge of locking disc 142 so that it will drop into locking notch 144 as soon as knot picker disc 117 reaches the unloading position (Fig. 20). At this position latch release block 218 has moved beneath latch release member 219 so that as soon as the nose of latching member 145 springs into recess 144 member 219 will be supported on block 218 as shown in Fig. 20 in full dotted outline. At this position also locking lever 164 has been tripped by roller 167 to release lug 165 so that needle carrier 137 can now move in the opposite direction to cause compressing member 163 to withdraw and needle 136 to uncover pocket 77 and release the bristle knot to the jaws of transfer

mechanism F (Fig. 50) which grasp the knot just prior to the uncovering of pocket 77.

Reverse movement of needle 136 takes place due to the change in contour of the needle carrier actuating cam 154, and the point of the needle recedes from its farthest position *o'* (Fig. 20) and commences to move clockwise. Release block 218 moves to the position shown by the dotted lines indicating its wedge-shaped head in Fig. 20. At this position *x'* pocket 77 is fully uncovered and the transfer mechanism F takes the bristles from the pocket. An instant later, at position *y'* the left edge of latch release block 218 moves out from beneath latch release member 219 thereby causing control lever 207 to fall and move latching lever 145 out of engagement with notch 144 of latch disc 142. This unlocks disc 117 so that it may commence to turn in the clockwise direction towards the loading position (Fig. 19) under the action of driving pin 148 on the needle carrier in engagement with lug 150 on disc 117. The unlocking does not occur until the longest bristles have left the pocket so that its return movement cannot distort the knot. During the first part of this return movement the right rise of resetting cam 220 engages roller 221 and lifts control lever 207 so as to bias the nose of latching lever 145 against the edge of disc 142 in readiness to cause the relocking of disc 117 as soon as it reaches the unloading position.

Knot transfer mechanism

The knot transfer mechanism F is shown in Figs. 47-56 inclusive (Sheet 13), and, in relation to the remainder of the machine, in Fig. 2A. This transfer mechanism comprises an elongated carriage 222 arranged to slide transversely of the machine on a stationary guide bar 223 which is mounted at its center by means of a bracket 224 (Figs. 50, 57, and 2A) on the frame of the apparatus. Carriage 222 is reciprocated by a link 225 which is connected at its front end to the carriage and at its rear end to a long pin 222a extending from an upright arm 226 (Figs. 57 and 58).

The purpose of this mechanism is to remove the knot from pocket 77 at the transfer or unloading position of knot picker disc 117 (Fig. 47) and insert the flag end of the knot a short distance within the ferrule at station 1 (Figs. 59, 68 and 1A). The range of the machine is increased by providing for the adjustment of the length of stroke of carriage 222. When the machine is running large brushes, that is brushes having long bristles, the stroke of this transfer carrier must be materially shortened. Also a small adjustment of the stroke facilitates the proper positioning of the flag ends of the bristles in the waiting ferrule. This adjustment is obtained by means of an arcuate slot in the upper end of arm 226 (Fig. 57) for its connection to the transfer carriage operating link 225. The radius of this slot is the length of link 225. Pin 222a forms the pivot and is mounted for adjustment in this slot.

This transfer mechanism is provided with jaws to compress the knot in two directions so as to make it both thinner and narrower than the knot in pocket 77 to facilitate its entrance into the ferrule and insure that all of the bristles are thus inserted. Arm 226 is at the rear of the machine and pivoted at its lower end at 227 to the machine frame (Fig. 57). Above this pivot the arm carries a roller 228 which cooperates with a channel cam in one face of a cam disc 229 which

is keyed to longitudinal slow-speed drive shaft 21.

The transfer jaws are shown in open position in Fig. 47 and in closed position in Fig. 48 where the bristle knot has been embraced by the jaws close to the forward edge of knot holder 116 (Fig. 50). The upper jaw 230 has a straight jaw portion 231 (Figs. 47 and 52) adapted to engage the upper side of the bristle knot. This jaw terminates at its outer end in a pair of tines 232 that are adapted to straddle the opposite sides of a narrow end portion 233 (Fig. 51) which projects to the right of the body of the lower jaw 234. Upper jaw 230 is mounted on upper jaw arm 235 by means of an L-shaped bracket 236. The jaw is longitudinally adjustable on the bracket, and the bracket is vertically adjustable on jaw arm 235, as indicated in Fig. 47. These two adjustments adapt upper jaw 230 to enclose knots of different width and thickness.

Lower jaw 234 is slotted as shown in Fig. 51 and within this slot is a yoke member 237 which carries a pair of tines 238 which cooperate with tines 232 in enclosing the opposite sides of the knot. Tines 238 straddle the body 231 of upper jaw 230 when the jaws close, this upper jaw body being narrower than that of the lower jaw. Yoke member 237 can be adjusted in slot to various widths of knot. Lower jaw 234 terminates at its left end in an L-shaped portion 239 which is vertically adjustable on lower jaw arm 240.

The transfer jaws 230 and 234 are so operated that in closing the two pairs of tines 232 and 238 move towards one another so as to compress the sides of the bristle knot. In other words the jaws have a compound closing and opening movement, namely, in closing they move simultaneously toward one another and lengthwise of one another in a direction to move tines 232 and 238 closer together, while their opening movement is a compound movement in the reverse direction. Consequently, in closing, the surfaces of the jaws and tines respectively move in two directions transverse to one another to compress the knot to reduce both its thickness and width.

This compound movement of the transfer jaws is accomplished by the mechanism shown in Figs. 46-51. A jaw supporting and operating shaft 241 extends longitudinally of transfer carriage 222 and is mounted in bearing brackets 242 and 243 which are mounted on the underside of the carriage at each end. Keyed to the forward end of shaft 241 outside of the front bearing bracket 242 is a double arm 244 which is forked at both upper and lower ends. Upper jaw arm 235 is pivoted in the upper fork and lower jaw arm 240 in the lower fork of this double arm 244. To the left of double arm 244 each of the jaw arms 235 and 240 have in them longitudinal slots 245 which receive rectangular blocks 246, each of which is mounted to swivel about a fulcrum pin 247 which projects from the front surface of front bearing bracket 242 (Fig. 51).

As the shaft 241 is rotated in the counter-clockwise direction as viewed in Fig. 47, it moves double arm 244 which in turn shifts the upper jaw arm 235 to the left and the lower jaw arm 240 to the right, and at the same time causes the righthand portions of the jaw arms to approach one another. Thus the jaws 230 and 234 are shifted from the position of Fig. 47 to that of Fig. 48 to clamp or squeeze the bristle knot in both directions.

The lower surface of body portion 231 of upper jaw 230 and the upper surface of the lower jaw 234 are not parallel with one another but slope

so that they are closer together at their outer edges than at their inner edges adjacent disc 117, that is, they flare toward the butt ends of the bristles. Thus the jaws conform to the taper of the bristles so as to distribute the clamping pressure evenly. The reduction in size of the bristle knot by the clamping action of the transfer jaws is indicated in dotted lines in Figs. 50 and 51.

10 The transfer jaw operating shaft 241 is actuated by the mechanism shown in Fig. 46. This comprises a cam 248 which is the innermost cam on knot picker cam shaft 28 of speed-reducer 27 (Fig. 2A). Cam 248 actuates a vertical lever 249 through follower roller 250, lever 249 being pivoted to the apparatus frame at its lower end and conducted at its upper end indirectly through a universal swiveling device, which will be described presently, to a link rod 251 which extends lengthwise of the machine towards the left. Connected to link rod 251 at its left end is a ball and socket joint 252 which is attached to a short arm 253 which in turn is fixed to the rear end of shaft 241.

25 The universal joint 252 is necessary in order to permit the motion of carriage 222 on guide bar 223 as well as the pivoting movement of lever 249. For the same reason a similar connection is required at the right end of link rod 251 between it and the upper end of operating arm 249. In addition it is desirable to provide a yielding connection for the operation of the transfer jaw clamping mechanism.

30 The operating connection shown in Fig. 46 may be used. This connection includes an extension member 263 having a hexagonal left hand portion and a reduced rod-like portion at the right of about the same diameter as rod 251. The hexagonal left portion is internally threaded and is 35 placed on the threaded end of link rod 251 where it is secured in adjusted position by means of a lock nut, as shown. The rod-like portion of extension member 263 passes freely through an aperture in a block 254. Block 254 is mounted for 40 both vertical and horizontal pivotal movement in the forked upper end 258 of lever 249, thus providing a connection between the lever and the link rod extension member 263 having freedom of movement in both directions. The forked upper end 258 of this lever is offset out of the plane of cam 248 as shown in Fig. 2A so as to place it nearer in line with the rear end of shaft 45 241 of the transfer mechanism.

45 A comparatively stiff helical compression spring 256 is confined on the rod-like portion of extension member 263 between block 254 and a nut 255 which is threaded on the outer end of this rod-like portion. As lever 249 pivots toward the right under the action of cam 248 to cause the transfer jaws 230, 234 to close by tensioning rod 50 251, the motion is imparted to the rod through the compression of spring 256 to close the jaws through the medium of this spring. Such compression of spring 256 produces a gap or space 55 257 between block 254 and the right end of the hexagonal portion of extension member 263. The amount of this gap is adjustable by adjusting the position of extension member 263 on rod 251 and the purpose of this adjustment will appear presently.

60 When the transfer mechanism has moved the bristle knot to the position shown in Figs. 59 and 68 where the ends of bristles are inserted in the ferrule at position 1, a transfer or entering pat- 65 ter 260 operates to pat or push the knot as far into

the ferrule as the transfer jaws 230, 234 will permit so that the bristles will be supported by the ferrule.

In order to allow transfer patter 260 to move the bristles and still have the bristles held under the control of the transfer jaws 230, 234, these jaws are slightly withdrawn from one another so as to partially release their clamping action on the bristle knot just as the patter commences to move the bristles forward through the ferrule. This partial release action is obtained by means of a segment 261 (Fig. 46) which is mounted on the side of cam 248 and is arcuately adjustable thereon by means of the clamping screw and slot connection indicated at 262. Lever 249 is at the right on the high part of cam 248 during the time that transfer jaws 230, 234 are transferring the bristle knot.

The drop-off near the lower side of segment 261 causes lever 249 to move block 254 to the left to not only completely close gap 257 but to contact the hexagonal shoulder of rod extension 263 to operate lever 253 through rod 251. The amount of partial release is dependent upon the length of gap 257. The longer this gap the more lost motion there is and consequently the less partial release. Conversely the smaller the gap the greater the release. The time that this release takes place depends upon where cam segment 261 is adjusted. Therefore the amount of release is dependent on the gap 257 and the time of release is dependent on the location of cam segment 261.

The modified form of transfer jaws illustrated in Figs. 53-56 enables a bristle knot having the maximum width of two inches (2") to be modified in dimensions so as to fit a ferrule for a two and one-half inch (2½") brush. The jaw construction is similar to that previously described except that the tines are arranged with an outward flare so as to allow the clamping action of the jaws to cause a spreading of the end of the knot which is toward the ferrule. However the clamping face of body 231a of the upper jaw and the clamping face of the body of lower jaw 234 slope inwardly as indicated by the dotted lines, and in a similar manner to jaws 230, 234 in order to accommodate the natural variation in the thickness of the bristle knot.

Thus tines 232a of the upper jaw, instead of being in alignment with one another parallel to the axis of the bristle knot, are disposed as shown in Figs. 53 and 54 in which the outer tine is farther from the center of the knot than the inner tine. Tines 238a of the lower jaw are similarly arranged, the same yoke construction being used as previously described. The mounting and adjustment of this modified form of yoke is illustrated in Figs. 55 and 56. It will be understood that the body portions, both of the upper and lower jaws, are modified to accommodate the sloping position of the two sets of tines 232a and 238a.

Fig. 101 illustrates diagrammatically the operation of this modified jaw construction. The flared type of jaws 230a, 234a have transferred the knot to place its forward end just within the end of a two and one-half inch (2½") ferrule at ferrule station 1. The forward portion of the bristle knot has been spread as indicated by the dotted lines so as to be wider than the rear portion to fit the extra wide ferrule. At the left end of Fig. 101 the bristle knot has been patted into the ferrule and the ferrule advanced to station 2. It will be understood that the remaining op-

erations on this extra wide brush unit will be the same as for the narrower brush units.

The transfer patter

5 This mechanism is shown in Figs. 57-68 inclusive. The pattering plate or patter proper 260 is mounted at the lower end of the linkage shown, and is operated in timed relation with the remainder of the knot picker mechanism, particularly the transfer jaws 230, 234. In Figs. 59 and 68 patter 260 is shown in its upper or extreme right position and in Fig. 57 it is on its downward stroke and comes in contact with the rear end of the bristle knot held by transfer jaws 230, 10 234 just after they reach their extreme left position adjacent the ferrule at position 1.

This swinging movement of the patter operating mechanism is brought about by a patter operating rod 264 which is connected at its left end to the patter mechanism and at its right end to an upright lever 265 (Figs. 57 and 58). This lever is loosely mounted at its lower end on a pivot shaft 266 to which it is operatively connected by means of a short arm 267 which is pinned to the right end of shaft 266. The upper end of arm 267 embraces lever 265 to transmit movement thereto and is provided on one side with a helical spring 268 (Fig. 57) for the purpose of providing a yieldable connection so that the forward stroke of patter 260 will be imparted through this yielding connection to safeguard against breakage if the patter should meet an obstruction. Pivot shaft 266 is oscillated by means of an arm 269 which is pinned at the left end of the shaft (Fig. 20 58), and which carries at its upper end a follower roller operating in a cam groove on the left face of cam disc 229. Operating rod 264 is connected to the upper end of lever 265 through an adjustable hand screw and slot connection indicated by numeral 270 (Fig. 57).

Referring now to the supporting and operating mechanism for transfer patter 260, the patter is provided on its rear surface with a short supporting member 271 which is pivoted at *w* and *z* respectively (Figs. 59 and 68) to the lower ends of a patter lever 272 (Figs. 62 and 63) and a parallel link 273. Patter lever 272 is pivoted about midway of its length on a pivot pin 274 which is fixed on the lower arm of a double-armed supporting lever 275 (Figs. 64 and 65). Supporting lever 275 is pivoted loosely at *x* (Fig. 59) adjacent the right end of a continuously rotating shaft 276 (Fig. 1A). This shaft is driven by a belt 277 from main operating shaft 13.

55 The second arm of double-armed supporting lever 275 is shown at 278 (Fig. 59) and at its upper end carries a horizontal pin (Fig. 61) to which one end of a tension spring 279 is attached, its lower end being attached to a similar pin 280 projecting laterally from a short lever arm 281 on patter lever 272. Spring 279 maintains a follower roller 282 mounted at the forked upper end of patter lever 272 in contact with a cam 283 which is keyed to continuously rotating shaft 276.

65 In this way a continuous vibrating or pattering motion is imparted to patter 260 through the rocking of patter lever 272 on pivot pin 274. Inasmuch as cam 283 is mounted on shaft 276 alongside of the hub of supporting lever 275, the lower portion of patter lever 272 is offset as shown in Figs. 60 and 63 to bring it into vertical alignment with parallel link 273, the lower ends of these members being connected to patter supporting member 271 in the same vertical plane. 70 Operating rod 264 for the patter mechanism is 75

27

connected to it at the right end portion of pivot pin 274 (Fig. 60).

The patter operating mechanism is constructed to impart a substantially parallel motion to patter plate 260 during the part of its travel in which it is acting upon the bristle knot to pat it into the ferrule. Thus the face of patter 260 is maintained in a substantially vertical position from the dotted line position 260a (Fig. 68) to the dot and single dash line position, 260b. In other words the face of patter 260 is maintained normal to the bristles or substantially at right angles to the axis of the bristle knot during the patting movement.

This parallel motion mechanism is as follows. The upper end of parallel link 273 is pivoted at *y* to a fulcrum or pivot shifting lever 284 (Figs. 66 and 67). This lever is pivoted at *x* by means of a hub portion 285 (Fig. 60) which surrounds shaft 276. Hub portion 285 is adjacent a bearing bracket 286 which supports shaft 276, but this hub is on the opposite side of bracket 286 from parallel link 273 and the remaining parts of the patter operating mechanism. Hence pivot shifting lever 284 has a somewhat S-shape as shown in Fig. 67 in order that the pivot pin for pivot *y* may extend to the left as shown in Fig. 60 into the plane of parallel link 273 which it supports. Fulcrum-shifting lever 284 carries two adjustable screws, namely stop screw 287 and contact screw 288. These screws are disposed in different angular position as shown more especially in Figs. 59 and 68. They are provided with lock nuts and may be fixed in adjusted position.

Stop screw 287 is adapted to engage the inner face of bearing bracket 286 as patter 260 is swung toward the left on its patting stroke by operating rod 264. Contact screw 288 is arranged to engage an ear 289 which projects laterally from supporting lever 275. A long tension spring 290 is attached at its upper end to a pin projecting from pivot shifting lever 284 and at its lower end to fixed bracket 286, and biases the lever 284 to swing about pivot *x* in the direction of bracket 286. Such movement of lever 284, however, is prevented by the engagement of the inner end of contact screws 288 with ear 289 on supporting lever 275, except under the control of operating rod 264.

The operation of this transfer patter operating mechanism is as follows. In discussing this operation, patter lever 272 and its supporting lever 275 will be considered as constituting a single lever pivoted to a shaft 276 at *x* and connected to the patter supporting member 271 at *w*. It will be assumed that the mechanism is at the extreme right position as shown in Figs. 59 and 68 and that operating rod 264 commences to move the mechanism on a forward stroke.

During about the first two-thirds (2/3) of this stroke, patter plate 260 moves to the position 260a by rotating about 276 where it begins to push or pat the bristle knot. At this instant the inner end of stop screw 287 contacts fixed bracket 286, an adjustment of this screw having previously been made for the particular length of bristles on which the machine is operating. During this portion of the forward stroke the entire operating mechanism including supporting lever 275 and pivot or fulcrum shifting lever 284, and all of their connected links and parts, swing about a common pivot, namely the point *x*. During this movement also the face of patter plate 260, which is in the extreme right position is at a considerable angle to the vertical, gradually approaches

28

the vertical position and reaches it at the point 260a.

When the end of stop screw 287 contacts bracket 286 the further swinging movement of pivot shifting lever 284 is arrested. This arrests the downward swing of pivot point *y* at *y'*, and from this point on parallel link 273 swings about this pivot point while the lever *wx* (patter lever 272 and supporting lever 275) swings about pivot point *x*. That is to say, while the patter plate is moved from the position 260a to its extreme left position 260b, lever *wx* swings from the dotted position of Fig. 68 to the dot and dash position, and link *y'z'* (parallel link 273) swings about the pivot *y'* from the dotted line position to the dot and dash position. The four pivots, *w*, *x*, *y'* and *z'* constitute approximately a parallelogram and the levers just described pivoting about these points approximately constitute a parallelogram linkage thereby maintaining the patting surface of patter plate 260 approximately normal to the axis of the bristle knot during the working stroke of the patter from position 260a to position 260b.

25
Ferrule feeding and bristle controlling mechanism

Early in the specification it was stated that the ferrules are fed from the bottom of a ferrule magazine D by a reciprocating conveyor or ferrule feed mechanism E (Figs. 1A, 1B, 69 and 71) through a number of successive equally spaced ferrule or brush unit positions or stations indicated by numerals 1-10. Stations 1-10 are shown in Figs. 1A and 1B and the first five of these stations are illustrated in greater detail in Figs. 69-71. It will be recalled that the ferrule feed mechanism is driven by crank 22 (Fig. 1B) and the double-armed lever 24. The ferrule feed mechanism comprises two spaced parallel feed bars 291 (Figs. 69 and 71) which extend along the front of the machine from the ferrule magazine D to the left or discharge end of the machine. The driving link 26 operatively connects the left ends of these bars with the double-armed lever 24. These two bars 291 are tied together by spacer blocks 292 (Figs. 71, 76 and 78) to which the bars are secured by machine screws as shown in Fig. 69, these blocks being distributed throughout the length of the feed bars.

Feed bars 291 are supported on two rollers 293 (Figs. 1A and 1B) which are recessed at each corner (Fig. 68) forming shoulders to guide the bars. Rollers 293 are mounted for rotation on yokes 294 (Figs. 59 and 75). Yokes 294 are mounted on the upper ends of shanks 295 which extend into the lower portions of brackets 296 (Figs. 59, 1A and 2A) that form a part of the frame of the machine and are laterally adjustable thereon. Brackets 296 move in slideways 296a and can be fixed in any desired position therein by means not shown. The lower ends of shanks 295 are threaded and provided with cooperating nuts (not shown) which are rotated through suitable bevel gearing (also not shown) operatively connected with a longitudinal shaft 297 (Figs. 1A and 1B) that extends between the two brackets 296 and may be turned by a hand wheel 298 so as to simultaneously raise or lower rollers 293 and therefore the ferrule feed bars 291.

The ferrules are supported throughout their travel from stations 1-10 between upper and lower stationary guide rails 299 and 300 (Figs. 69, 71 and 78). Each of these rails is composed

of a metal backing member having a facing in contact with the ferrules of suitable friction material such as wood or fiber. This construction is indicated by the section lining in Figs. 71 and 78 and also in other cross-sectional views. The upper ferrule guide rail 299 is made in longitudinal sections as shown in Fig. 71 for ease of replacement due to wear, and the facing material for the lower ferrule rail 300 is also made in sections of the same length for a similar purpose, although the backing member of the lower rail is a continuous metal bar.

The sections of upper rail 299 are yieldingly supported on a stationary channel member 301 which is mounted at the upper ends of brackets 296. Each rail section has a pair of vertical rods 302 extending upwardly through vertically aligned apertures in the flange portions of channel member 301 as shown for example in Figs. 71 and 77. Compression springs are placed on rods 302, the upper end of each bearing against the upper channel flange portion and the lower end of each engaging a collar 302a. Collars 302a are adjustably mounted near the lower ends of rods 302 (Fig. 68), and are adjusted to bring the lower surface of the individual rail sections into horizontal alignment with one another.

The lower ferrule guide rail 300 is supported on rollers 303 flanged as shown in Fig. 77 and 68 (Sheet 16) and appropriately spaced along the length of and between the two ferrule feed bars 291. Lower feed rail 300 extends to the right beyond the right end of feed bars 291 and is held in stationary position by means of a connection (Fig. 1A) to the machine frame which permits limited movement of the bar both horizontally and vertically so as not to interfere with the adjustment in these two directions of the ferrule feed mechanism as a whole. By this is meant the lateral adjustment of brackets 296 and the vertical adjustment of the feeding mechanism which is accomplished by turning hand wheel 298 as previously described. This connection consists of a short vertical rod 304 (Fig. 1A) fixed at its upper end to the end of guide rail 300 and received with a sliding fit in a bore in a block 305. Block 305 in turn has a horizontal stem 306 (Fig. 2A) which makes a sliding fit in a horizontal aperture in an adjacent part of the machine frame.

It will be understood that the facing portions of the ferrule guide rails 299 and 300 are suitably grooved lengthwise to receive the central rib of the ferrules. Such groove is indicated for the lower rail in Fig. 91. The ferrules are held stationary at stations 1-10 by their frictional engagement with the two rails.

The ferrules are shifted from station to station by means of dog members 307 which are pivoted in uniformly spaced relation between the two feed bars 291. Each of these dog members 307 is U-shaped as shown in Fig. 75, the upper ends of the two legs engaging the ferrule, and is mounted on a pivot pin 308 which extends between feed bars 291 and has a coil spring surrounding it as shown in Fig. 75. This biases the upper ends of the dog members towards their positions above the upper surface of the lower bristle rail 300 as shown in Fig. 71. A stop pin 309 is provided to fix such position of each of the dog members.

The ferrules are fed one at a time from the bottom of ferrule magazine D by means of a pickup device 310 which is mounted at the right end of feed bars 291 (Fig. 73). The pickup de-

vice is U-shaped in cross section as shown in Fig. 74, its two legs extending upwardly inside of bars 291 with clearance with the sides of stationary ferrule guide 300. Pickup device 310 may be adjusted vertically with respect to feed bar 291 in order to accommodate a thinner or a thicker ferrule. The device may also be adjusted lengthwise of the feed bars in order that it may position the ferrules properly at station 1. This adjustment is obtained by the two pairs of cross slots shown in Fig. 73 and the two adjusting nuts 311 which are threaded on the ends of cross bolts 312 (Fig. 74). It will be understood that stationary guide rail 300 is provided with an elongated slot within which these bolts move during the reciprocation of feed bars 291.

Bristle control rail mechanism

After the transfer pater 260 has pushed the bristle knot into the ferrule at station 1 as far as the thickness of the transfer jaws 230, 234 will permit, and the ferrule feed mechanism E commences to advance the ferrules with the bristles within them to station 2 and the successive stations, there is a tendency for the bristles to become displaced in the ferrule because of the weight of the portion of the bristle knot which overhangs the ferrule and because of vibration of the machine. This is particularly true when running short bristles since the length of the bristles within the ferrule at station 1 is quite short and the proportion of overhang is considerable. For the purpose of overcoming this difficulty, upper and lower bristle controlling rails 313, 314 have been provided (Figs. 78, 73, 69 and 71).

Upper bristle control rail 313 is mounted in stationary position on channel member 301, but is arranged for both horizontal and vertical adjustment so as to properly position the lower edge of the rail with respect to the bristles overhanging or projecting from the rear ends of the ferrules. These rails extend from position 1 through position 5. As shown in Fig. 70 upper bristle control rail 313 is held in position by means of spring loaded clamps as follows: Blocks 316 and 323 are fastened to the inside of channel 301 and have each a bored aperture to receive a stepped sleeve 315. At the bottom of this aperture is a threaded hole.

Screws 317 having heads 318 which bear against the rear surface of rail 313 are threaded into these holes. These screws project through these apertures beyond the front of channel member 301 and have operating handles 319 pinned to their forward ends. The lateral adjusting movement of rail 313 is positive in both directions by the turning of screws 317, spring 320 keeping sleeve in contact with the rail and in turn the rail is kept in contact with the heads of the screws.

In order to permit vertical adjustment of upper guide rail 313 the rear portions of screws 317 pass through vertical slots in these rails one of which is shown at 321 in Fig. 73. The vertical adjusting movement is provided by means of two hand screws 322 (Figs. 71 and 78) which are threaded at their lower ends into two blocks 323 and 323a. The upper portions of screws 322 have cylindrical grooves 324 which are engaged by an L-shaped yoke member 325, the vertical portion of which is attached to the rear face of guide rail 313 (Fig. 78). Rail 313 is retained in any vertical position by the clamping pressure of springs 320.

The lower bristle guide rail 314 is not stationary but moves with the reciprocating ferrule feed bars 291, being mounted thereon. The mountings for rail 314 provide for a vertical adjustment of the rail with respect to the feed bars and also for a lateral adjustment which is obtained by a pivoting movement of the rail, indicated by the dotted line position shown in Fig. 76.

The body portions of these mountings are the spacer blocks 292 for the two feed bars 291. These spacer blocks are each provided with narrowed downward extensions (Fig. 76) the sides of which are engaged by the upwardly directed legs 325 (Fig. 76) of an adjustable support 326. Supports 326 each carry two horizontally projecting pivot pins 327, and rails 314 have at their opposite ends two downwardly projecting supporting lugs 328 (Fig. 71) which are apertured to receive these pins. Rail 314 may therefore swing from the full line to the dotted position shown in Fig. 76 about these pins 327 as pivots. Each of these pins is equipped with a coil spring adapted to bias rail 314 into contact with the inner feed bar 291.

Hand screws 329 are threaded in apertures in blocks 292 and contact supporting lugs 328 above pivot pins 327, and by turning these screws the angular position of rail 314 may be adjusted. The vertical adjustment is obtained by means of two additional hand screws 330 (Fig. 71) the inner portions of which are threaded into spacer blocks 292. Turning these screws in one direction serves to raise the supporting members 327 and thus also raise the bristle rail. Turning them in the opposite direction lowers the rail under the action of coil springs arranged on these screws and within suitable recesses in members 326 (Fig. 76).

These two bristle control rails 313, 314 are positioned in the same vertical plane directly back of the line of the rear ends of the ferrules, and practically touching the ferrules as they are shifted from one station to the next. These rails are of metal and about one-eighth of an inch in thickness. The transfer jaws 230, 234, when in position to deliver a bristle knot to the ferrule at station 1, approach close to and practically touch the bristle control rails. The flag ends of the bristles consequently project somewhat more than one-eighth of an inch from the surface of the transfer jaws in order to enter the ferrule.

It is necessary for bristle control rail 313, 314 to clamp or squeeze the bristles in the ferrules at the several ferrule or brush unit stations 1-5 inclusive in order to carry out their function of preventing the bristles from falling out of the ferrules due to vibration or to gravity. Consequently the edges of rails 313, 314 must be spaced closer together than the thickness of the ferrules as shown for example in Figs. 69 and 71. In view of this there is a tendency for the rails to partially obstruct the entrance to the ferrule at station 1 and thus interfere with the insertion of the end of the bristle knot by the transfer jaws 230, 234.

This is overcome by sloping off the forward or right end portion of lower rail 314 as is indicated by dotted lines at 331 in Figs. 69 and 73, and by providing upper control rail 313 with a pivoted end section 332 (Fig. 72) which can be swung upward into the dotted position shown in Fig. 73. In this figure lower bristle rail 314, which is mounted on rear ferrule feed bar 291, has been shifted to the left with the feeding movement

of these bars, Fig. 73 showing feed bars 291 in their extreme left position.

This feeding movement carries an empty ferrule from the magazine D to station 1 and also places the sloping end 331 of lower bristle rail 314 to the left of position 1, so that with the pivoted section 332 of upper bristle rail 313 lifted, the transfer to the ferrule is unobstructed by the edges of the bristle control rails. The bristle knot can therefore be inserted by the transfer jaws 230, 234 without difficulty.

The mechanism for operating the pivoted upper bristle rail section 332 to raise it to the dotted position of Fig. 73 and to lower it into 15 clamping position with the bristles in the ferrule at station 1 is illustrated in Figs. 70, 72, 73 and 75. Pivoted end section 332 is arranged in vertical alignment with rail 313 and accordingly is mounted on the inner face of a plate 333 (Figs. 20 72 and 75) which in turn is pivoted at 334 to the rear flat surface of rail 313, provided with a suitable upward end extension for this purpose. Pivot 334 is formed by a bolt as shown in Fig. 75 on which a coil spring is placed to maintain 25 the surface of plate 333 and rail 313 always in flat contact with one another, and thereby to maintain pivoted extension 332 in alignment with the bristle rail.

Plate 333 is provided with an upwardly projecting tongue 335 to which tension spring 336 is connected and which serves to bias end section 332 about pivot 334 towards its clamping or bristle engaging position as shown in Fig. 71 and 72. An adjustable limiting stop member 337 (Fig. 35 72) having a hook portion 338 (Fig. 75) to engage the forward edge of tongue 335 serves to properly position the lower edge of extension 332 in line with the lower edge of rail 313.

The swinging movement of pivoted end section 40 332 from one of its positions to the other is effected by means of a substantially vertical lever 339, having a latch member 340 pivoted slightly more than half way down its length and terminating at the bottom in a flat pad 341. This 45 lever is swung back and forth as will presently appear by the reciprocating movement of ferrule feed bars 291 and causes the swinging movement of end section 332 by the contact of a roller 342 carried on the rear face of lever 339 with tongue 50 335. Lever 339 is pivoted at its upper end to a gooseneck bracket 343 bolted to the top of channel member 301.

Latch member 340 is adapted to engage a stationary pin 344 which projects horizontally from 55 the face of the right supporting bracket 296 and is provided with an actuating finger 345 (Fig. 73) which extends downwardly adjacent to pad 341 on the end of lever 339. Latch 340 is biased upwardly by a tension spring and is also provided with an upwardly extending projection to engage an adjustable stop screw 346 to hold the sloping head of the latch in position so that it will automatically snap past stationary pin 344. Lever 339 is swung toward the left to cause the 60 intended latch engagement as shown in Fig. 73.

In the operation of this mechanism, starting with the parts in the position shown in Fig. 73, the ferrule feed bars 291 being at their extreme left position, now commence to move toward the right leaving the several ferrules at their several 70 stations. As feed bars 291 approach their right-hand position, an actuator 347, in the form of an adjustable screwhead mounted on the front feed bar, meets and actuates finger 345, swinging latch 75 340 about its pivot on lever 339 and releasing it

from pin 344. Further motion brings latch 340 in contact with pad 341 of lever 339 and causes it to swing to the right, which in turn allows pivoted rear section 332 to swing to its operative position as shown in Fig. 72, the force of spring 336 operating through tongue 335 following up roller 342 on lever 339 which is being moved to its right-hand position (Fig. 69).

This occurs after the transfer jaws 230, 234 have moved up and inserted the end of the bristle knot in the ferrule at position 1, and also after transfer patty 260 has patted the knot into the ferrule. Also the movement of feed bars 291 toward the right has carried the sloping end portion 331 of lower bristle rail 314 beyond ferrule station 1 so that the bristles within the ferrule have now been engaged by both bristle rails and are ready to be advanced to station 2 in a semi-clamped condition. This occurs after the feed bars 291 have completed their movement toward the right and the dog members 307 have snapped past the ferrules at the several stations and are in the position shown in Fig. 69.

The left-hand or feeding stroke of feed bars 291 now takes place and the ferrules are shifted one station, a new ferrule from magazine D being moved by pickup device 310 to station 1. Substantially at the end of this forward stroke, a second actuator 348 similar to the first but mounted in a different position on the same feed bar 291, engages pad 341 at the lower end of lever 339 and swings it toward the left so that latch 340 re-engages pin 344. This movement also, through the engagement of roller 342 with tongue 335, causes pivoted section 332 to be swung to its open position, ready for the insertion of the next knot at station 1. It is well to note that the improved transfer jaws of the present invention impart a two-direction squeeze to the knot, which reduces both the thickness and width of the knot to such an extent that the knot does not fill the ferrule until the wedge or plug is inserted, which does not take place until the brush unit reaches station 5. However, the upper and lower control rails 313 and 314 compress the knot to a still smaller thickness and thus force the bristles against both sides of the ferrule, this condition being shown for example in Figs. 69 and 71. This tends to make the knot and ferrule in effect a rigid unit so that the knot and ferrule can more readily be transferred from one station to the next by the ferrule acting as a driver for the rigid knot inside of it.

The card mechanism

As the ferrules are moved along from station to station by the reciprocating feed conveyor bars 291, the bristles projecting from the rear ends of the ferrules ride between the edges of the two bristle control rails 313, 314. Since the upper rail is stationary, the bristles in the knots of the several brush units slide in contact with it and the friction causes some of the bristles of the various knots to drag toward the right and partially distort the knots. The lower bristle control rail does not produce such an effect while the brush units are in motion because this rail is then moving with the brush units. However when feed bars 291 return toward the right to their initial position carrying the lower control rail with them, such friction effect is also produced by that control rail sliding under the stationary knots. The direction of the drag and the tendency to distort the bristles is the same as that produced by the upper control rail. Such distortion is overcome by the card mechanism.

This card mechanism is illustrated in Figs. 84-89 inclusive and parts of it are also shown in the cross-sectional views (Figs. 77 and 78). A rectangular bar 349 (Fig. 89) is arranged for lengthwise sliding movement in an elongated head member 350 which is bolted to the outer end of a supporting arm 351 (Fig. 83) by which vertical movement is imparted to head 350. Rectangular bar 349 is provided with three groups of long slender needle-like vertical teeth somewhat similar to textile carding teeth. These groups are indicated at 352, 353, 354, and the arrangement is such that these teeth are projected upwardly simultaneously through the bristles of the brush units at positions 2, 3 and 4, directly in the rear of these units close to the bristle guide rails 313 and 314 (Figs. 77 and 78). The three groups of teeth travel toward the left, at the same speed as feed bars 291 carrying the brush units from stations 2, 3 and 4 to stations 3, 4 and 5, respectively during the next feeding movement of these bars. Whereupon the teeth are withdrawn below the bristle knots and are returned to their original positions at stations 2, 3 and 4 to again operate on the succeeding feeding movement on bars 291.

The mechanism for bringing about this vertical shifting of the card carrier bar 349 is as follows. Arm 351 which supports head 350 at its front end, is pivoted centrally at 355 (Figs. 2A and 83, Sheet 30 14) on a pedestal secured to the frame of the apparatus. At its rear end, arm 351 carries a follower roller 356 which cooperates with the periphery of a cam disc 357 keyed to slow-speed shaft 21. This cam disc includes an adjustable cam segment 358 (Fig. 83) which controls the duration and timing of the downward movement of head 350. Carding head 350 is shifted downward by cam segment 358 and is moved upwardly by means of a tension spring 359. An adjustable stop 40 360 is provided to set the extent to which the carding teeth pierce the bristles.

Card carrier bar 349 is supported for sliding movement in head 350 by means of two guide extensions 361 at the opposite ends of the head. 45 The carrier bar is retained in these guides by means of a plate 362 which extends along the front of head 350 as shown in Fig. 84 and is held in place by screws 363 on the lower part of each guide extension. A cover plate 364, the right 50 edge of which extends over the top edge of bar 349, retains it in the guides at the top. The individual carding teeth have enlarged base portions 365 by which the teeth are mounted in bar 349. These base portions extend up through a 55 slot (Fig. 89) between the right edge of cover plate 364 and the left margin of front plate 362. This slot is closed by a strip 366 having a multiplicity of holes to receive the teeth and which move with them to prevent the entrance of stray 60 bristles.

It is desirable to maintain the support of the butt ends of the bristles projecting from the ferrules at the several stations as continuously as possible by the teeth of the card mechanism. 65 Consequently the card carrier bar 349 is reciprocated in such a manner as to shift the several groups of teeth 352, 353, 354 out of engagement with one set of brush unit bristles and into engagement with the next succeeding brush unit 70 bristles as quickly as possible.

This is accomplished by the following mechanism. Card carrier bar 349 is driven by ferrule feed bars 291 during the left-hand or feeding movement of these bars. Carding head 350 is 75 then lowered to withdraw the three groups of

card teeth from the brush units at stations 3, 4 and 5 respectively, and carrier bar 349 is shifted quickly to the right by means of a spiral spring, whereupon the carding head is again raised to bring the card teeth into engagement with the bristles of the succeeding brush units at stations 2, 3 and 4.

The flat spiral spring referred to is shown at 367 (Figs. 84 and 86), its inner end being secured to a vertical supporting post 368 and its outer end being attached at 369 to a part 370 which is fixed to the rear side of carrier bar 349.

Part 370 has a downward extension 371 adapted to be engaged by a roller 372 (Fig. 71) mounted at the lower end of a bracket which is secured to feed bars 291 (Fig. 69). This roller transmits the left-hand motion of ferrule feed bar 291 to extension 371 and thus to carrier bar 349. At the extreme left end of the feed stroke a lug 373 on the rear of extension 371 engages a spring-biased latch member 374 pivoted beneath the left end of head 350 (Fig. 84). Hence on the return stroke, toward the right, of feed bars 291, card carrier 349 remains latched in stationary position.

Substantially at the end of the right-hand feed stroke of bars 291 head 350 carrying card 349 is depressed by cam segment 358 rocking arm 351.

This lowers the card teeth out of the bristles at stations 3, 4 and 5, and in its downward movement the tail of latch 374 strikes a stationary adjustable stop 375 (Fig. 71) thus tripping the latch and releasing the carrier bar 349 which travels rapidly to the right under the action of spring 367 whereupon the card teeth are instantly raised by the action of cam 358 and returned into engagement with bristles of the next brush units at stations 2, 3 and 4. In order to cushion the stopping of carrier 349 at the end of its stroke under the action of the spiral spring, a dashpot mechanism 376 (Fig. 87) is arranged at the right-hand end of head 350. The piston of this mechanism is actuated by a second lug on the rear of extension 371.

Final operations on brush units

The card mechanism just described assists in conveying the brush units as far as the cardboard plug inserting mechanism G at station 5 (Fig. 2A). As the brush units pass from station 4 to station 5 the butt end of the bristle knot which projects from the rear of the ferrule is acted upon by a spreading knife 377 (Figs. 90 and 91). This is a slender wedge-shaped member and serves to divide the knot along its longitudinal center line into two portions, and to spread these upper and lower portions apart to receive the end of a cardboard strip 378 at station 5. This strip is severed by an upwardly moving knife blade 379 cooperating with a stationary blade or ledger plate 380 (Fig. 90), these being parts of the cardboard inserting mechanism G. This leaves a cardboard plug 381 (Fig. 96) supported by the bristles of the knot with a portion of it projecting slightly.

The spreader knife 377 is provided with a slotted shank through which a pair of screws extend to clamp the spreader to a supporting bracket 382. This slot provides longitudinal adjustment of the spreader, and vertical adjustment is obtained by shifting bracket 382 which is held by screws 383. Cardboard plug 381 consists of only a single thickness of cardboard, but it will be understood that a number of cardboard strips similar to strip 378 may be fed in super-

posed position to the cutting knives 379 and 380 in order to insert a multilayer plug if desired. Also it will be understood that, if desired, the retaining plug may be made of any suitable material.

5 The cardboard inserting mechanism G, which includes mechanism (not shown) for operating the cut-off knives and a cardboard strip feeding device (also not shown), is described in detail in the prior patent mentioned at the beginning of this specification, and reference to such patent may be had for an understanding of these details. This inserting mechanism is operated by a cam on shaft 21, as indicated in Fig. 2B.

10 When the brush unit feed mechanism E (feed bars 291) transfers the brush unit from station 5 to station 6, there is a tendency for the cardboard plug 381 to be jarred loose from the bristle knot. To avoid this a plug carrier 384 (Figs. 90 and 91, Sheets 3 and 6) in the form of a small endless belt is arranged to contact the rear end of the cardboard insert or plug 381 shown in Fig. 96 to retain the plug in position and to travel with the plug during the feeding movement of feed bars 291.

15 To impart the desired motion to endless carrier 384 the mechanism shown in Figs. 90 and 91 is employed. Belt 384 is carried on two small idler pulleys 385, 386 and a driving pulley 387. Driving pulley 387 is secured to the upper end 20 of a small shaft 388 which is supported for rotation by the arms of a bearing bracket 389. At the center of shaft 388 a small drum 390 is fixed on which is wound a cord 391 while at the lower end of shaft 388 a spool 392 is loosely mounted which contains a spiral spring 393. The inner end of spring 393 is secured to shaft 388 so as to rotate the same, and the outer end of the spring is fixed to the outer portion of the spool. 25 The spring may be wound to the desired extent by turning spool 392, which is then secured in fixed position by means of a forked member 394 (Fig. 92) which is held by a removable plug or screw 395 on the lower arm of bracket 389.

30 Cord 391 which is wound around drum 390 has its outer end carried to the left and secured at 396 to the rear reciprocating feed bar 291. The arrangement is such that as the feed bars 291 move toward the left cord 391 will be carried with them thereby unwinding it from drum 390 and rotating shaft 388, moving belt 384 at the same linear speed as the feed bars. On the back stroke of feed bars 291, spring 393 will cause rotation of shaft 388 in the opposite direction and thus wind cord 391 onto drum 390.

35 Instead of employing the plug carrier 384, ledger plate 380 may be constructed with an extension to support the plug and retain it within the bristle knot. Such a construction is shown in Fig. 90a (Sheet 3) where the ledger plate is indicated by numeral 380a and the extension by numeral 384a. The extension is offset below the ledger plate in order to align it with the path of the plug cut from strip 378a. The ledger plate extension is preferably made of highly polished hardened steel so as to present as little friction as possible to the plug.

40 When the ferrules arrive at station 6, they are 45 acted upon by a final patting mechanism 397 (Fig. 1B) which pats the bristle knot and its plug 381 nearly flush with the rear end of the ferrule as shown in Fig. 97. In order to hold the ferrule during this patting movement, a ferrule stop 398 is provided. This is shown in Figs. 93, 94 and 95 (Sheet 5). Stop 398 is mounted by means of

screws on the outer surface of the upper ferrule guide rail 299 and is provided with a lip 399 which projects along its bottom edge to engage the ferrule along its upper edge adjacent the bristle knot.

Patting mechanism 397 is operated from slow-speed shaft 21 by means including a cam 400 and a link 401 (Fig. 2B) so as to swing the patty forward to drive in the bristles at the proper time. This patting mechanism is of the vibrating type such as previously described, the vibration of the patty plate being produced by means of a cam on rotating shaft 276 (Fig. 1B). A similar patting mechanism is used at station 3 to drive the bristle knot into the ferrule the correct distance to receive the cardboard plug. These patting mechanisms are set forth in detail in the prior patent previously referred to.

As the brush unit or ferrule feed bars 291 transfer the units between positions 6 and 7 the trimmer H, which is preferably in the form of a rotary trimming device, similar to a hair clipper, trims off the odd bristles such as indicated in Fig. 100 which may still project. This trimming device is operated by belt 402 from high-speed shaft 13.

No operation is performed on the brush units at stations 2, 7 and 8, these stations being included for convenience in the arrangement of the apparatus.

The bristle knot pulling mechanism I at station 9 comprises upper and lower jaws 403 and 404 which are operated by suitable mechanism to cause the jaws to clamp the opposite flat sides of the knot projecting from the ferrule at station 9 and then move horizontally outward together so as to pull the knot including the cardboard plug 381 to final position in the ferrule. This position is shown in Fig. 98 and in dotted lines in Fig. 99. Sufficient space is left beyond the butt ends of the bristles for the bristle cement and the handle, both of which are added in a separate machine. A ferrule stop 405 similar to stop 398 is required at station 9 as indicated in this figure and also in Fig. 98. Knot pulling mechanism I is operated from slow-speed shaft 21 through a cam in the right-hand face of a cam disc 406 (Fig. 2B). Associated with this cam is a follower which is mounted in the upper end of an arm 407 (Fig. 1B) keyed on the end of a short shaft on the opposite end of which is keyed a second and longer arm 408. Arm 408 is connected through a link 409 (not shown) to the knot pulling mechanism. Details of this mechanism are disclosed in the prior patent previously mentioned.

At the final brush unit station 10, the final combing mechanism J operates to straighten the bristles of the knot after they have been pulled to their final location in the ferrule by the pulling mechanism I. The comb 410 is mounted at the end of a vertical bar which is operated by a double crank mechanism indicated generally by numeral 411, this mechanism being driven by means of a belt 412 from main drive shaft 13. Reference may be had to the same prior patent mentioned for further details of this final combing mechanism.

The improved construction of the present machine provides full support of the bristles both during and subsequent to the formation of the knot so as not only to prevent the loss of bristles but to obtain a properly and uniformly shaped knot. Moreover the knot is supported in such a way that the flag end portions as well as the

butt end portion cannot sag and become distorted from the desired shape during the movements required prior to its insertion in the ferrule. The handling of the knot, from the time of its original formation until insertion in the ferrule, is carried out in such a way as to insure complete control of the bristles at all times, and in addition the proper shaping of the knot to facilitate insertion in the ferrule without loss of bristles, and particularly in such a way to insure that a properly shaped knot is inserted in every ferrule. The handling of the brush units after the insertion of the bristle knots therein is carried out by the apparatus in a similar way so that the brush units issue from the delivery end of the machine with uniformly well shaped and full bristle knots therein. These and other advantageous features of the machine resulting from the improved construction of the invention disclosed herein mutually contribute to a substantial increase in the output of the machine, and to enable the machine to produce a better and a more uniform product. In addition the improvements of the present invention provide for the ready adjustment of all of the various mechanisms which handle the bristles, the bristle knots and the ferrules at different stages of brush unit manufacture and are so arranged and constructed that the machine can be set up in a very few minutes to produce any size of brush unit within its range.

The improved construction of the present invention has been described herein in connection with one particular embodiment. It will be understood that the invention is not limited to the particular forms of construction shown and described, but that the scope of the invention is intended to extend to such changes or modifications as may be included within the terms of the appended claims.

I claim:

1. In a brush machine, a bristle knot forming unit comprising a knot carrier having a bristle holding pocket, means for operating said carrier to move said pocket alternately between a bristle receiving position and a bristle discharge position, a bristle feed box for supplying bristles to said pocket comprising a floor arranged to support the bristles, a roof member for confining the bristles to the width of said pocket, and guides for the ends of the bristles, said floor being constructed and arranged to support the flag ends of the bristles which have been received in said pocket, a needle member on said carrier movable to segregate the bristles within the pocket from those in the feed box, a movable knot shaper constructed and arranged to cooperate with said floor to support the flag end portion of the knot of bristles in said pocket to prevent distortion of said knot and means for operating said knot shaper in timed relation to the movement of said carrier.

2. In a brush machine, a bristle knot forming unit comprising a knot carrier having a bristle holding pocket, means for operating said carrier to move said pocket alternately between a bristle receiving position and a bristle discharge position, a bristle feed box for supplying bristles to said pocket comprising a floor arranged to support the bristles, a roof member for confining the bristles to the width of said pocket, guides for the ends of the bristles adjustable to accommodate bristles of different length, a floor extension to support the butt ends of the bristles received in said carrier pocket, a floor extension to support

the flag ends of the bristles, means for adjusting said support for different length bristles, a movable knot shaper adapted to coat with said floor extension and with said roof, and means for operating said shaper in timed relation to the movement of said carrier.

3. In a brush machine having a bristle knot forming unit comprising a knot carrier having a bristle holding pocket, and means for operating said carrier to move said pocket alternately between a bristle receiving position and a bristle discharge position, a bristle feed box for supplying bristles to said pocket comprising a floor to support the bristles, guides for the ends of the bristles, a substantially vertical feed finger adapted to move bristles in said box towards said pocket, said floor having a slot therein, and means to operate said finger with its lower end within said slot and below the surface of said floor.

4. In a brush machine, a bristle knot forming unit comprising a rotary knot carrier having a bristle holding pocket, means for operating said carrier to move said pocket alternately between a bristle receiving position and a bristle discharge position, means at said receiving position for feeding a supply of bristles towards said pocket to load the same, a needle associated with said carrier to segregate the bristles within said pocket from the supply and close the pocket to form a knot, means for actuating said needle to close the pocket at said bristle receiving position and to open said pocket at the discharge position, locking mechanism for securing said carrier against movement at both said positions thereof, said locking mechanism being operative to maintain said carrier locked during the loading of said pocket at the bristle receiving position and during the removal of said bristles at said discharge position.

5. In a brush machine, a bristle knot forming unit comprising a rotary knot carrier having a bristle holding pocket, means for operating said carrier to move said pocket alternately between a bristle receiving position and a bristle discharge position, means at said receiving position for feeding a supply of bristles towards said pocket, a needle associated with said carrier to segregate the bristles within said pocket from the supply and close the pocket to form a knot, means for actuating said needle to close said pocket at the bristle receiving position and to open said pocket at the discharge position, locking mechanism for securing said carrier against movement at both said positions thereof, means for releasing said locking mechanism after movement of said needle has closed said pocket at said receiving position, and means for releasing said locking mechanism at the discharge position subsequent to the removal of said knot.

6. In a brush machine, a bristle knot forming unit comprising a rotary knot carrier having a bristle holding pocket, means for operating said carrier to move said pocket alternately between a bristle receiving position and a bristle discharge position, means at said receiving position for feeding a mass of bristles towards and into said pocket, a needle associated with said carrier, means for actuating said needle to move the point thereof through the mass of bristles and segregate therefrom the bristles within said pocket to form a knot, a separator finger to cooperate with the needle, and mechanism for moving the said finger first into the bristle mass alongside the needle and then away from the needle in a direction lengthwise of the bristles to effect separation of

the end portions of the knot bristles from those of the mass.

7. In a brush machine, a bristle knot forming unit as set forth in claim 6 in which mechanism 5 is associated with the separator finger to impart thereto a continuous rapid lateral vibration as the finger moves lengthwise of the bristles.

8. In a brush machine, a bristle knot forming unit comprising a rotary knot carrier having a bristle holding pocket, means for operating said carrier to move said pocket alternately between a bristle receiving position and a bristle discharge position, means at said receiving position for feeding a mass of bristles towards and into said pocket, a needle associated with said carrier, means for actuating said needle to move the point thereof through the mass of bristles and segregate therefrom the bristles within said pocket to form a knot, a separator finger directed oppositely to 10 the needle, mechanism for moving the said finger first into the bristle mass alongside the needle and then away from the needle in a direction lengthwise of the bristles to effect separation of the end portions of the knot bristles from those of the mass, locking mechanism for securing said carrier against movement at said receiving position and means for releasing said locking mechanism after said finger has completed its separating operation.

9. In a brush machine, a bristle knot forming unit comprising a rotary knot carrier having a bristle holding pocket, means for operating said carrier to move said pocket alternately between a bristle-receiving position and a bristle-discharge position, means at said receiving position for feeding a mass of bristles towards and into said pocket, a needle associated with said carrier, means for actuating said needle to move the point thereof through the mass of bristles and segregate therefrom the bristles within said pocket to form a knot, a separator finger to cooperate with the needle, and mechanism for operating said separator finger comprising a rotatably supported shaft, a mounting fixed thereon and to which said finger is secured, means for imparting angular movement to said shaft to cause said finger to move into the bristle mass alongside of said needle, and means for subsequently moving said shaft lengthwise to cause said finger to travel lengthwise of the bristles to separate the end portions of the bristles of the knot from those of the mass.

10. In a brush machine, a bristle knot forming unit as set forth in claim 9 which is provided with an adjustable stop for limiting the lengthwise movement of the separator finger shaft to correspond with the length of the bristles.

11. In a brush machine, a bristle knot forming unit comprising inner and outer concentric rotatably mounted shafts, a knot carrier loosely mounted on said outer shaft, and having a bristle holding pocket adapted to hold a knot of bristles in substantially parallel relation to said shafts, a needle associated with said knot carrier, a needle carrier to support said needle and fixed to said outer shaft to be actuated thereby, a separator finger to cooperate with said needle, a separator mounting fixed to said inner shaft to be operated thereby and arranged to support said finger in a direction opposite to and substantially parallel with said needle, operative connections between said needle and knot carrier members whereby the operating movement of the knot carrier is imparted from the needle

carrier, means at a receiving position of said pocket for feeding a mass of bristles towards and into said pocket, means for rotating said outer shaft to cause said needle to move through the mass of bristles and segregate therefrom a knot of bristles within said pocket and thereafter to rotate said knot carrier to move the pocket to a discharge position, mechanism for rotating said inner shaft in timed relation to the movement of said outer shaft to cause the separator finger to move into position alongside of said needle while said pocket remains at said receiving position, and means for imparting lengthwise movement to said inner shaft to move said separator finger parallel therewith and lengthwise of the bristles to separate the end portions of the bristles of the knot from those of the mass.

12. In a brush machine, a bristle knot forming unit comprising a rotary knot carrier having a bristle holding pocket, means for operating said carrier to move said pocket alternately between a bristle receiving position and a bristle discharge position, means at said receiving position for feeding a supply of bristles towards said pocket, a needle associated with said carrier to segregate the bristles within said pocket from the supply and close the pocket to form a knot, means for actuating said needle to close the pocket at said bristle receiving position and to open said pocket at the discharge position, a compressing member on the carrier constructed and arranged to compress the whole knot to frictionally clamp the bristles in said pocket, and means for actuating said compressing member prior to the commencement of movement of said carrier away from said bristle receiving position.

13. In a brush machine, a bristle knot forming unit comprising a rotary knot carrier having a pocket for holding a bristle knot, said carrier being angularly movable to shift said pocket alternately between a bristle receiving position and a bristle discharge position, a needle member shiftable with respect to said carrier to close and open said pocket, a needle carrier mounted coaxially with said knot carrier and operable to actuate said knot carrier between said receiving and discharge positions, a compressing member on the carrier constructed and arranged to compress the knot in said pocket, means for operating said compressing member after the pocket is closed by the needle, mechanism for thereafter locking said carriers against relative movement, and means for releasing said locking mechanism when the knot carrier pocket reaches the discharge position.

14. In a brush machine, a bristle knot forming unit comprising a rotary knot carrier having a bristle holding pocket, said carrier being angularly movable to shift said pocket alternately between a bristle receiving position and a bristle discharge position, a needle member shiftable with respect to said carrier to close and open said pocket, a needle carrier mounted coaxially with said knot carrier and operable to actuate said knot carrier between said receiving and discharge positions, said bristle pocket having a slot in one side thereof, a compressing member adapted to enter said slot and positioned on said needle carrier to compress the needles in said pocket after the pocket is closed by the needle, mechanism for thereafter locking said carriers against relative movement, and means for releasing said locking mechanism when the

knot carrier pocket reaches the discharge position.

15. In a brush machine, means for feeding ferrules successively to a bristle inserting station, means for feeding a mass of bristles, means for separating successive groups of bristles from said mass to form knots, means for aligning said successive knots with the ferrule at said station, and mechanism for receiving the knot from said aligning means and inserting it in said ferrule, said mechanism including compression surfaces movable in two directions transverse to one another to compress the knot to reduce both its width and thickness.

16. In a brush machine, means for feeding ferrules successively to a bristle inserting station, means for feeding a mass of bristles, means for separating successive groups of bristles from said mass to form knots including flag end separating mechanism, means for aligning said successive knots with the ferrule at said station, and mechanism for receiving each knot from said aligning means and inserting it in said ferrule, said mechanism including compressing surfaces movable in two directions transverse to one another to compress the knot to reduce both its width and thickness.

17. In a brush machine, means for feeding ferrules successively to a bristle inserting station, means for feeding a mass of bristles, means for separating successive groups of bristles from said mass to form knots including flag end shaping mechanism, means for aligning said successive knots with the ferrule at said station, and mechanism for receiving each knot from said aligning means and inserting it in said ferrule, said mechanism including compression surfaces movable in two directions transverse to one another to compress the knot to reduce both its width and thickness.

18. In a brush machine, means for feeding ferrules to a plurality of successive stations, means for feeding a mass of bristles, means for separating successive groups of bristles from said mass to form knots, means for aligning said successive knots with the ferrule at one of said stations, mechanism for receiving each knot from said aligning means and inserting it in said ferrule to form a brush unit, mechanism at a succeeding ferrule station for performing a further operation on said brush unit and a pair of edgewise spaced bristle control rails extending between said stations to engage the upper and lower surfaces of the knots in proximity to the ferrules to prevent dislocation of said bristles.

19. In a brush machine, means for feeding ferrules successively to a plurality of successive stations, means for feeding a mass of bristles, means for separating successive groups of bristles from said mass to form knots, means for aligning said successive knots with the ferrule at one of said stations, mechanism for receiving each knot from said aligning means and inserting it in said ferrule to form a brush unit, mechanism at a succeeding ferrule station for performing a further operation on said brush unit, a pair of edgewise spaced bristle control rails extending between said stations adapted to engage the upper and lower surfaces of the knots in proximity to the ferrules, and means for adjusting said rails to cause them to squeeze the bristles in the respective ferrules to prevent dislocation thereof.

20. In a brush machine, means for feeding ferrules successively to a plurality of successive stations, means for feeding a mass of bristles, means

for separating successive groups of bristles from said mass to form knots, means for aligning said successive knots with the ferrule at one of said stations, mechanism for receiving each knot from said aligning means and inserting it in said ferrule to form a brush unit, mechanism at a succeeding ferrule station for performing a further operation on said brush units, a pair of edgewise spaced bristle control rails extending between said stations adapted to engage the upper and lower surfaces of the knots in proximity to the ferrules, said rails operating to squeeze the bristles in the respective ferrules to prevent dislocation thereof, and mounting devices for said respective rails, said devices including means to adjust the spacing therebetween and means to shift said rails laterally, to accommodate knots of different sized brushes.

21. In a brush machine having means for feeding ferrules successively to a plurality of successive stations, means for feeding a mass of bristles, and a knot forming unit to separate successive groups of bristles from said mass to form knots including a bristle holding pocket, mechanism for packing a full pocket of bristles, a flag end shaping device and flag end separating means, the combination of means for aligning said successive knots with the ferrule at one of said stations including means for compressing each knot in the direction of its width, mechanism for receiving the knot from said aligning means and inserting it in said ferrule, said mechanism including means to compress the knot to reduce both its width and thickness, mechanism at a succeeding ferrule station for performing a further operation on said brush units, a pair of edgewise spaced bristle control rails extending between said stations adapted to engage the upper and lower surfaces of the knots in proximity to the ferrules, said rails operating to squeeze the bristles in the respective ferrules to prevent dislocation thereof.

22. In a brush machine having means for feeding ferrules successively to a plurality of successive stations, means for feeding a mass of bristles, and a knot forming unit to separate successive groups of bristles from said mass to form knots including a bristle holding pocket, mechanism for packing a full pocket of bristles, a flag end shaping device and flag end separating means, the combination of means for aligning said successive knots with the ferrule at one of said stations including means for compressing each knot in the direction of its width, mechanism for receiving the knot from said aligning means and inserting it in said ferrule, said mechanism including means to compress the knot to reduce both its width and thickness, mechanism at a succeeding ferrule station for performing a further operation on said brush units, a pair of edgewise spaced bristle control rails extending between said stations adapted to engage the upper and lower surfaces of the knots in proximity to the ferrules, said rails operating to squeeze the bristles in the respective ferrules to prevent dislocation thereof, and mounting devices for said respective rails, said devices including means to adjust the spacing therebetween and means to shift said rails laterally, to accommodate knots of different size brushes.

23. In a brush machine, means for feeding ferrules successively to a bristle inserting station, means for feeding a mass of bristles, means for separating successive groups of bristles from said mass to form knots, means for aligning said suc-

cessive knots with the successive ferrules at said station, means for receiving each knot from said aligning means and inserting it in said ferrule comprising a pair of cooperating jaws to grasp said knot and mechanism for actuating said jaws into and out of engagement with said knot, mechanism for impelling said knot into said ferrule while the knot is still held between said jaws, means for partially releasing the pressure of said jaws prior to the commencement of said impelling operation, and means for maintaining said jaws in contact with the bristle knot under a lesser pressure during the impelling operation.

24. In a brush machine, means for feeding ferrules successively to a bristle inserting station, means for feeding a mass of bristles, means for separating successive groups of bristles from said mass to form knots, means for aligning said successive knots with the successive ferrules at said station, means for receiving each knot from said aligning means and inserting it in said ferrule comprising a pair of cooperating jaws to grasp said knot, said jaws being constructed and arranged to squeeze the knot to reduce both thickness and width and mechanism for actuating said jaws into and out of engagement with said knot with both a clamping and a shifting motion, mechanism for impelling said knot into said ferrule while the knot is still held between said jaws, means for partially releasing said jaws prior to said impelling operation, and means for maintaining said jaws in contact with the bristle knot under a lesser pressure during the impelling operation.

25. In a brush machine, means for feeding ferrules successively to a bristle inserting station, means for feeding a mass of bristles, means for separating successive groups of bristles from said mass to form knots, means for aligning said successive knots with the successive ferrules at said station, means for receiving each knot from said aligning means and inserting it in said ferrule comprising a pair of cooperating jaws to grasp said knot and mechanism for actuating said jaws into and out of engagement with said knot, mechanism for impelling said knot into said ferrule while the knot is still held between said jaws, said jaw actuating mechanism including means for partially releasing the engagement of said jaws with the knot substantially simultaneously with the contact of said impelling mechanism with said knot, and means for varying both the timing and the degree of said release to accommodate knots of different length and size.

26. In a brush machine, means for supporting bristles in approximate parallelism, a patting device to even said bristles by impacting the same at one end, said device including a bristle impacting member having a substantially flat surface, and mechanism for operating said patting device including means to maintain the surface of said impacting member substantially normal to the axis of the bristles, and means for adjusting said impacting member closer to or farther from the ends of said bristles.

27. In a brush machine, means for supporting a ferrule, means for supporting a bristle knot with one end thereof projecting within said ferrule, a patter plate adapted to engage the opposite end of said knot to impel the same farther into said ferrule, and mechanism for operating said patter plate to cause it to approach said ferrule including means to maintain the surface thereof

substantially normal to the axis of the bristle knot.

28. In a brush machine, means for feeding ferrules successively to a bristle inserting station, means for forming and aligning successive bristle knots with the successive ferrules at said station, transfer mechanism including a pair of cooperating jaws for receiving a knot from said aligning means and clamping it therebetween, said transfer mechanism operating to advance the knot to said ferrule and insert one end of said knot therein, and patting mechanism for impelling said knot further into said ferrule comprising a patter plate and operating mechanism therefor, means for actuating said patter operating mechanism to hold said plate out of the path of said transfer mechanism and to move said patter into engagement with said knot after said transfer mechanism has advanced the knot to the ferrule, said patter operating mechanism including parallel-motion mechanism to maintain the face of said patter plate substantially square with the end of the knot while said plate is patting the same.

29. In a brush machine, means for feeding ferrules successively to a bristle inserting station, means for forming and aligning successive bristle knots with the successive ferrules at said station, transfer means including a pair of cooperating jaws for receiving each knot from said aligning means and clamping it therebetween, said transfer means operating to insert one end of said knot within said ferrule, and patting mechanism for impelling said knot further into said ferrule comprising a patter plate and operating mechanism therefor, means for actuating said patter operating mechanism to hold said plate out of the path of said transfer mechanism and to move said patter plate into engagement with said knot after said transfer means has advanced the knot to the ferrule, said patter operating mechanism including parallel-motion mechanism to maintain the flat face of said patter plate substantially normal to the axis of the knot while said plate is in contact therewith, means for partially releasing said jaws prior to the engagement of said patter plate with said knot, and means for maintaining said jaws in contact with the bristle knot under a lesser pressure during the impelling operation.

30. In a brush machine, means for feeding brush units successively to a plurality of stations, each of said units including a ferrule and a bristle knot having its butt end projecting therefrom, a spreading device for dividing the projecting end of said knot into two sections, means for feeding a strip of wedge material between said sections, severing means to cut said strip to deposit a wedge member between said sections, a wedge carrier arranged to engage the severed end of said wedge, and means for causing said carrier to travel at the same speed as said brush unit feeding means.

31. In a brush machine, means for feeding brush units successively to a plurality of stations, each of said units including a ferrule and a bristle knot having its butt end projecting therefrom, a spreading device for dividing the projecting end of said knot into two sections, means for feeding a strip of wedge material between said sections, severing means to cut said strip to deposit a wedge member between said sections, and a wedge carrier comprising an endless belt mounted to travel parallel with the path of said brush units, and means operatively connecting said belt

with said brush unit feeding means to cause said belt to operate simultaneously therewith.

32. In a brush machine, means for feeding brush units each including a ferrule and a bristle knot having its butt end projecting therefrom, said feeding means comprising a pair of vertically spaced ferrule guide rails arranged to frictionally support the ferrules between them, a reciprocating feed bar having a series of spring-biased dog members to feed the ferrules to a plurality of stations spaced along said feed rails, and a card support having a plurality of groups of teeth constructed and arranged to engage the bristles projecting from the ferrules at a plurality of said stations, means for moving said support at the same speed as said ferrule feed bar on its forward stroke, means for imparting a quick return motion to said card support on its back stroke, and means for raising said support at the beginning of its forward stroke to project said teeth through the bristles and for lowering said support at the end of its forward stroke to disengage said teeth from the bristles.

33. In a brush machine, means for feeding ferrules successively to a bristle inserting station, means for moving bristle knots successively into alignment with the ferrule at said station, and mechanism for receiving the knot from said aligning means and inserting it in said ferrule, 30 said mechanism including compressing surfaces movable in directions transverse to one another to compress the knot to reduce both its width and thickness to facilitate the entrance of the knot into the ferrule.

34. In a brush machine, means for feeding brush units successively to a plurality of stations, each of said units including a ferrule and a bristle knot having its butt end projecting therefrom, a spreading device for dividing the projecting end of said knot into two sections, means to deposit a wedge member between said sections, and a barrier member positioned in contact with the severed end of said wedge to retain the wedge between said bristle sections as the brush unit moves to the next station.

35. In a brush machine, means for feeding brush units successively to a plurality of stations, each of said units including a ferrule and a bristle knot having its butt end projecting therefrom, a spreading device for dividing the projecting end of said knot into two sections, means for feeding a strip of wedge material between said sections, severing means to cut said strip to deposit a wedge member between said sections, and a stationary barrier member having a smooth vertical surface positioned to contact the severed end of said wedge to retain the wedge between said bristle sections as the brush unit moves to the next station.

36. In a brush machine, a bristle knot forming unit comprising a knot carrier having a bristle holding pocket, means for operating said carrier to move said pocket alternately between a bristle receiving position and a bristle discharge position to discharge successive knots, means at said receiving position for feeding a mass of bristles toward and into said pocket, a needle associated with said carrier, means for actuating said needle to move the point thereof through the mass of bristles and segregate therefrom the bristles within said pocket to form a knot, a separator finger to cooperate with the needle, mechanism for moving said finger into the bristle mass alongside the needle and thereafter away from the needle in a direction lengthwise of the bristles

to a predetermined distance from the ends of the bristles, said mechanism operating to maintain said finger in this position during the movement of said pocket to discharge position and substantially until its return to the receiving position to receive a succeeding knot, said finger thereby acting as a barrier to prevent loss of bristles from said mass.

37. In a brush machine, a bristle knot forming unit as claimed in claim 1 wherein the knot shaper cooperates with the roof as well as with the floor of the bristle feed box.

38. In a brush machine, a bristle knot forming unit as claimed in claim 1 wherein the knot shaper engages the top and the exposed vertical faces of the knot.

39. In a brush machine, a bristle knot forming unit as claimed in claim 1 wherein the floor of the bristle feed box is provided with a longitudinal groove, and the knot shaper has a vertical bar portion to engage with the vertical exposed face of the bristle knot, said bar portion terminating in a tongue which operates within said groove to prevent damage to the bristles.

40. In a brush machine, a bristle knot forming unit as claimed in claim 1 wherein the knot shaper cooperates with an extension of the floor of the bristle feed box, and the knot shaper and said floor extension are arranged for adjustment laterally of the bristle feed box to accommodate bristle knots of different lengths.

41. In a brush machine, a bristle knot forming unit as claimed in claim 1 wherein provision is made for changing the thickness and width of the bristle holding pocket to accommodate knots of different size, the bristle feed box being adjustable to correspond to change in width of the bristle holding pocket, and wherein the knot shaper is also arranged to be adjustable both as to the thickness and width of the bristle knot so as to correspond with changes in the size of said pocket.

42. In a brush machine, a bristle knot forming unit as claimed in claim 6 wherein the bristles are fed through a feed box into the bristle holding pocket to form the knot, and there is provided a movable knot shaper constructed and arranged to cooperate with the feed box to support the knot substantially at its flag end to prevent distortion, and the movement of the separator finger away from the needle continues until the finger is adjacent the knot shaper.

43. In a brush machine, a bristle knot forming unit as claimed in claim 6 wherein the movement of the separator finger away from the needle continues until the finger is adjacent the flag ends of the bristles, and the finger is held in this position during the operation of the knot carrier to act as a barrier to assist in retaining the bristles in the feed box.

44. In a brush making machine, a bristle knot forming unit comprising a knot carrier having a bristle holding pocket device, means for operating said carrier to move the pocket of said device alternately between a bristle receiving position and a bristle discharge position, a bristle feed box with supplying bristles to said pocket including a floor and means to feed bristles

through said feed box and into said pocket, said pocket device comprising a member fixed to said carrier and a replaceable insert member, said fixed member having a lip forming one side wall of the bristle holding pocket, said lip being in alignment with the floor of the bristle feed box when said pocket device is in the receiving position, and said replaceable insert having a block portion with a lip at one side only and constructed and arranged to form the bottom and opposite wall respectively of said pocket, whereby the size of the bristle pocket may be changed by replacing said replaceable insert.

45. In a brush making machine, a bristle knot forming unit as claimed in claim 44 wherein the bristle feed box includes a roof member with provision of means for adjusting said member to align it with the lip on the replaceable insert.

46. In a brush making machine, a bristle knot forming unit as claimed in claim 44 in which the fixed member of the bristle holding pocket device has a slideway arranged parallel with the lip on said member, and the replaceable insert is provided with a formation constructed and arranged to cooperate with said slideway, means being provided to retain said insert from displacement along said slideway.

47. A brush machine as claimed in claim 33 wherein the compressing surfaces which reduce the width of the knot flare towards the flag end of the knot and reduce the width of its butt end portion while causing the flag end portion to expand so as to fit a ferrule having a larger width size than that of the knot as held in the aligning means.

48. In a brush machine, means for feeding ferrules to a plurality of successive stations, mechanism for inserting a knot of bristles in the ferrule at one of said stations to form a brush unit, mechanism at a succeeding ferrule station for performing a further operation on said brush unit, and a pair of edgewise spaced bristle control rails extending between said stations to engage the upper and lower surfaces of the knots in proximity to the ferrules to prevent dislocation of said bristles.

49. A brush machine as claimed in claim 48 wherein the ferrules are advanced from station to station by a reciprocating conveyor, the bristle control rails being arranged close to and parallel with the ferrule conveyor and disposed vertically one above the other.

50. A brush machine as claimed in claim 49 in which the upper bristle control rail is mounted in stationary position, and the lower bristle control rail is mounted on and reciprocates with the ferrule conveyor.

Certificate of Correction

Patent No. 2,513,016

June 27, 1950

MELVIN J. FIRST

It is hereby certified that error appears in the printed specification of the above numbered patent requiring correction as follows:

Column 1, line 6, for the word "accompany" read *accompanying*; column 5, line 9, for "device of" read *device on*; column 8, line 34, for "cooperate" read *cooperates*; column 20, line 57, for "seel" read *steel*; column 22, line 58, for "flang" read *flag*; column 42, lines 11 and 37, for "compression" read *compressing*; column 44, line 13, for "impeller" read *impelling*; column 45, line 17, after "patter" insert *plate*; column 47, line 67, for "with" read *for*;

and that the said Letters Patent should be read as corrected above, so that the same may conform to the record of the case in the Patent Office.

Signed and sealed this 3rd day of October, A. D. 1950.
